AUTOMATIC STOCK QUOTATION BOARD

Clyde Smith, Hopkinsville, Ky., assignor, by
mesne assignments, to International Standard
Electric Corporation, New York, N. Y., a cor-
poration of Delaware

Application October 10, 1929, Serial No. 398,634

17 Claims. (Cl. 177—353)

The present invention relates to an automatic stock quotation board system with means for registering stock designations, the quantity of shares sold and the prices of the previous close, open, high, low and last quotations of the stock selected.

In carrying out the invention, it is proposed to register substantially on the same lines as the ticker now prints, namely for registering a series 10 of sales as: AX-15.116 $\frac{3}{4}$ .10.3 $\frac{1}{4}$ .1 $\frac{1}{2}$ .1 $\frac{1}{4}$ .1 $\frac{1}{8}$, where AX represents the stock designation of the stock selected, 15 represents the quantity of shares sold in 15 hundreds, 116 $\frac{3}{4}$ the full price if, say, it be the first sale of the day, followed by a series of sales indicating the sale of a block of 1000 shares at $\frac{3}{4}$ or 116 $\frac{3}{4}$, and other sales at 116 $\frac{1}{2}$, 116 $\frac{1}{4}$ and 116 $\frac{1}{8}$. With the present system, the stock will be selected once, the full price sent once, and the following sales of the same stock will register quantity and such part of the price as may be significant, i. e., if the hundreds, tens, units remain unchanged, the fraction only need be changed, if the fraction is changed from the preceding quotation. If the price remains unchanged, the 20 quantity only need be sent, even though the quantity be the same as the last sale and consequently involving only the operation of parts of the system, increasing the output of the system, and resulting in saving time and apparatus movement. 25

While the system provides for selection of stock, shelf, quantity and price, the full range of selection need not always be made.

For purposes of illustration, only four code discs, of the conventional form as well understood 30 in the art, are used for registering and selecting stocks. This selection is brought about by the use of one set of code discs to select fifteen stocks. With four code discs 16 possible selections may be had. Preferably, one position is made inactive. 35 However, the system employs two sets of code discs, each for the selection of fifteen stocks. Utilizing both sets of discs, 225 selections may be had for double letter selection in addition to 30 selections for single letter stocks, making a total of 255 possible selections.

With the use of five discs in each set of stock selecting registers, the range of selection may be increased to 1023, if one inactive position is provided. Employing five discs, 32 combinations are 40 possible. One position being inactive, 961 double letter combinations are possible, which, in addition to the 62 selections for single letter stocks, makes a total of 1023 possible selections. With this method of selecting, the time of transmission 45 is materially reduced.

The invention is designed to be operated by a standard telegraph typewriter transmitter for selecting 30 or 62 stocks, depending upon the number of registering code discs employed having a single letter designation, and 255 or 1023 stocks 5 with two letter designations, although, of course, the embodiment of the invention described herein is not to be limited to this precise number.

An object of the invention resides in the method and means whereby the stock and shelf, quantity 10 and price group relays may be selectively nominated for selecting certain control relays, which in turn determine which of the several groups of recording relays will be utilized and held in circuit for taking up the code record from a line re- 15 lay and for transmitting the record in its received or translated form to the stock selector registers and dial operating circuits.

In recording a sale as AX-999-236 $\frac{3}{4}$, three nominating operations are necessary, one for nominating the stock and shelf group relay, one for nominating the quantity group relay, and one nominating operation for the price group relay. In the example chosen, AX is a double letter stock, thus two stock selecting operations are needed, 25 one to select letter A of the odd register, and another selection for X in the even column of registers. For registering the quantity 99,900 shares, three selections are required, one selection for the nine ten thousands, one for the nine thousand 30 and one for the nine hundreds. The system is designed to register the quantity sales in hundreds. Quantities less than 100 shares will not be registered.

Four selections are needed to register the full 35 price at 236 $\frac{3}{4}$, that is, one selection of the two hundreds, one for the three tens, one for the six units, and lastly, one for the three quarters of the fractions, if this be the first quotation of the day. Once the price is registered, only the changing 40 portions of the price would be subsequently sent, quantities, however, being always sent in the series of sales.

The expression AX is a double letter stock designation and may refer to any well known 45 stock, as for example, International Telephone and Telegraph Corporation.

Quantity of shares need not always be registered, as in times of big markets, as is now done with the ticker, thus eliminating the operating 50 time of the quantity group relay and associated control, transfer and recording relays which are prevented from being placed in circuit to actuate the quantity control dial circuits to control the quantity drive shaft code disc circuits. 55

Another object of the invention is in the provision of novel means for employing the hundreds and tens price relays for registering quantities, and the units and fraction price relays for registering the price, where the price is in one integer and a fraction and the quantity is to be indicated in quantities from 100 to 9900 shares.

The invention provides a novel guard circuit beginning at the stock selectors and extending to the shelf, quantity and price selectors. Where 10 to 15 a stock and price selection is involved in a quotation, the shelf and quantities are omitted, and the price control relays are held guarded against operation until the stock selection is completed. Following this selection, the price relays become operative, so that each control relay in each group and each group of control relays will be operated in their proper sequence.

Where a stock, quantity and price selection 20 is involved in a quotation, and the shelf is omitted, the quantity and price relays are held guarded against operation until the stock, quantity and price selection is completed. However, the quantity and price relays become operative 25 after the complete selection for stock, quantity and price has been made, so that each control relay selected in each group and each group of control relays selected will operate in their proper sequence.

30 In addition to the above objects, the guard circuit also serves to energize the last of the series of guard relays, and hold locked the recording relays, if energized, the guard circuit preventing the operation of a change over relay, 35 if any of the control relays in the quantity group is energized; the guard circuit, from group to group of the control relays, also serves to insure the proper sequence between the groups of the various relays on the selecting operation.

40 Another object of the invention is to restrain the operation of the disc operating coils or magnets for setting the stock registers, quantity and price drive shafts to predetermined positions until the operating pulse has been received in the recording relays.

45 Another object of the invention resides in the provision of means for automatically setting groups of switches to predetermined positions corresponding to the numerical order selected, and in the provision of means for transferring 50 the switching circuits for either single or double letter stock selection.

The invention comprehends the utilization of 55 automatic means for restoring the quantity dials to blank, following the operation of dial actuating shafts together, with means for zero setting code discs of the stock registering selectors preparatory to resetting the code discs for registering predetermined stock designations.

60 Broadly, the invention includes time controlled means for transmitting a preliminary electrical impulse to energize a series of group relays, and a subsidiary group of relays comprising a pair of polar relays for nominating a particular group 65 relay in the series, in addition to a receiving distributor, electrically associated with groups in pairs of control relays having a common group relay of the series and a column of recording relays controllable by a transfer relay which is 70 responsive to the release of a relay of a pair of control relays to operate disc setting coils of the stock selector registers and dial operating circuits and drive shaft code disc coils.

75 Other objects and advantages will be disclosed as the description herein proceeds and it is ob-

vious that modifications may be made in the embodiment of the automatic system set forth without departing from the invention, as claimed.

In the accompanying drawings there is shown, for purposes of illustration only, the preferred 5 schematic arrangement of the present invention, showing a layout of a system for recording stock designations in single or double letters, the quantity of shares sold, and the price of the stock selected, it being understood that the drawings 10 show, by way of example, one only of the many possible embodiments of the invention wherein,

Figures 1 to 10 inclusive show schematically the complete system, but illustrate four stock dial groups only, and reading from left to right, 15 the upper portion of the system includes,

Figure 1 as a fragmentary portion of the system showing the receiving distributor, the timer, the nominating and subsidiary relays, and portions of the circuits for the group, control and 20 recording relays, and the stock selector registers.

Figure 2 is a portion of the system showing the control relays and associated guard relays for stock and shelf selection, and groups of recording relays, each provided with a transfer relay. This view also shows the wipe out relays and the slow relay associated with the zero setting 25 circuits of the stock register selectors.

Figure 3 is a part of the system showing the 30 group relay for the stock and shelf control relays and the group relay for the quantity control relays and associated guard relays, and groups of recording relays cooperating with a transfer relay associated with the control relays, in addition to the change over relay and portions of the various circuits associated with all these 35 relays, mentioned, and,

Figure 4 shows a part of the system illustrating the group relay for price selection, and the 40 associated, control, guard, transfer and recording relays and portions of the circuits of the system associated with these relays.

Reading from left to right, the lower portion of the system comprises four views of which, 45

Figure 5 shows the odd and even stock selector registers and associated circuits, in addition to the shift relays and circuits for single or double letter stock selection.

Figure 6 is also a fragmentary view of the 50 system showing portions of the various circuits, and also the switching group for single letter odd stock selection.

Figure 7 is a fragmentary view of the switching system for single letter even stock selection 55 and for double letter stock selection.

Figure 8 shows a portion of the system including the price and quantity drive dial code disc shafts and a shift relay having a plurality of contacts for transferring price circuits to register 60 quantities.

Figure 9 is a fragmentary view of the code disc drive dial shafts and the branch shafts on which the various groups of dial units are mounted.

Figure 10 is a schematic view of four dial groups 65 comprising two stocks for single letter selection and two dial groups for double letter stock selection.

Figure 11 is a diagrammatic view of the arrangement of the views, comprising the system 70 above described briefly.

A general description of the system will first be given. In Fig. 1 is disclosed a receiving distributor A controlled by a sending distributor (not shown) at a master station (likewise not 75

shown). Associated with the distributor A are cams 12 and 30, nominating relays 15 and 18, and subsidiary relays 43—46, and 103. Referring to Figs. 2, 3 and 4, price group relay 701 is adapted to be initially energized over conductor 101A by the action of cam 30 and to be locked over conductor 32A, which is controlled by the nominating relays and predetermined subsidiary relays; quantity group relay 47 and shelf group relay 27 are adapted to be initially energized over conductor 32, after price group relay 701 has been operated, by the action of cam 30, and to be locked over conductors 109 and 202 which are closed by the operation of predetermined subsidiary relays. Associated with the price group relay 701 are price control relays 709—712 and 721—724; associated with the quantity group relay 47 are quantity control relays 53—57; and associated with combined stock and shelf group relays 27 are stock control relays 23, 24, 28, 29, and shelf control relays 51 and 52. The control relays associated with any group relay are placed under control of distributor A when the associated group relay is operated. Locking circuits, as between relays 28 and 24, relays 54 and 55, etc., and their guard relays, as 74, 77 and 213, are provided for placing only one pair of control relays, as 23 and 28, under control of distributor A at a time, and subsequently placing the remaining operated control relays under control of the distributor, pair by pair, in a predetermined sequence.

Associated with the control relays are groups of relays, as K, K1, L, M—M2 and N—N3. Each group, as K, is associated with a pair of control relays, as 23 and 28, and contains a transfer relay, as 69, and four recording relays, as 37—40. The function of the transfer relays, as 69, is to place the four recording relays, as 37—40, under control of distributor A when one of a pair of control relays, as 23, is released and the other, as 28, is operated. The recording relays in the several groups, as K, K1, etc., when placed under control of distributor A by the operation of the associated transfer relay, are adapted to be selectively operated over conductors 19, 20, 21 and 22 in accordance with impulses transmitted from the master station. It is to be noted that the locking circuits and guard relays mentioned above permit only one group of recording relays, as K, to be selectively operated at a time, and the several groups of recording relays are operated in a definite sequence.

In Fig. 5 are illustrated stock selectors O and O1; in Figs. 6 and 7 stock selector switches P—P5; in Fig. 10 groups of indicators for displaying quotations on stocks Q—Q3; and in Figs. 8 and 9 a system of shafting for positioning these indicators.

The stock selector O is driven by a shaft 318, which is in turn driven through shaft 327 and friction clutch 328 (Fig. 8) by a continuously operable motor 914. This motor also serves to drive stock selector O1 through friction clutch 350, shaft 348, and shaft 323. Each of the stock selector switches is provided with a plurality of wipers, mounted on a common shaft, which are adapted to move over associated contact banks. The common shaft 346 of switch P and the common shaft 347 of switch P1 are adapted to be driven by shaft 327, which also drives shaft 318 of stock selector O. The common shafts 911, 915, 916 and 917 of switches P2, P3, P4 and P5, respectively, are adapted to be driven by shaft 348, which also drives shaft 323 of stock selector O1.

The stock selector O is adapted to be operated over conductors 38A, 39A, etc., by the recording relays of group K, to permit the shaft 327 to be driven to a predetermined position and then stopped by the freeing of friction clutch 328. 5 Shafts 346 and 347, on which the wipers of switches P and P1 are mounted, are thus moved to a predetermined position and the wipers of these switches are brought to rest on predetermined contacts. A relay 310, associated with stock selector O, is operated whenever O is operated and serves to connect circuits as 334, 412, 413, etc. to switch P. The operating magnets, as 1—11, associated with the indicators of a predetermined stock, as Q, are thus placed under 15 control of the recording relays in the groups L, M—M2, N—N3.

Similarly, the stock selector O1 is adapted to be operated over conductors 240, 241, etc. by the recording relays of group K1, to permit shaft 348 20 to be driven to a predetermined position and then stopped by freeing the friction clutch 350. Shafts 911, 915—917, on which the wipers of switches P2—P5 are respectively mounted, are thus moved to a predetermined position and the 25 wipers of these switches brought to rest on predetermined contacts. A relay 313, associated with stock selector O1, is operated whenever O1 is operated and serves to connect circuits, as 334, 412, 413, etc., to switch P2. The operating magnets, as 12—22, associated with the indicators of a predetermined stock, as Q1, are thus placed under control of the recording relays in groups L, M—M2 and N—N3. 30

When both stock selectors O and O1 are operated, neither relay 310 nor 313 is energized, and the circuits, as 334, 412, 413, etc. are connected to switch P1. Switch P1 serves to extend these circuits through one of the switches, as P3—P5, to the operating magnets, as 23—33, associated 40 with the indicators of a predetermined stock, as Q2, and to place these operating magnets under control of the groups of recording relays L, M—M2 and N—N3. 45

Referring to Fig. 8, the shafts 501—507 are each provided with code selectors R—R6 respectively. Code selector R, when variably operated by the recording relays of group M, is adapted to permit the shaft 501 to be moved to a predetermined position and then stopped by the 50 freeing of the friction clutch 526; code selector R1, when variably operated by the recording relays of group M1, is adapted to permit the shaft 502 to be moved to a predetermined point and then stopped by the freeing of the friction clutch 529. Similarly, the other code selectors R2—R6, when variably operated by the recording relays of groups M2 and N1—N3, permit the shafts 503—507 to be moved to predetermined points by freeing the friction clutches 570, 510, 60 etc. 55

It is thus evident that the shafts 508—598F, etc., driven by shafts 501—507, can be set to any predetermined position. It was indicated above that the operating magnets, as 1—11, as 65 associated with the indicators of a predetermined stock, as Q, might be placed under control of the recording relays in groups L, M—M2 and N—N3. When the recording relays in these groups are selectively operated by the distributor A, predetermined operating magnets are energized and the indicators, as 900, 901, 902, etc., associated with the operated magnets, are set to a position in accordance with the position of the shaft whereon they are mounted. 70 75

In Fig. 8 a relay 52! is shown for causing the recording relays of group N, which ordinarily control the operation of code disc R3 associated with shaft 504, to control the operation of code disc R1 associated with shaft 502; and for causing the recording relays of group N!, which ordinarily control the operation of code disc R4 associated with shaft 505, to control the operation of code disc R2 associated with shaft 503. Also in Fig. 3 a relay 98 is illustrated for connecting the conductors 742 and 765, controlled respectively by the recording relays of groups N and N!, to the conductors 295 and 422, ordinarily controlled by the recording relays of groups M! and M2, respectively. The last mentioned conductors, when extended by the stock selector switches, as P1, P2, P3, etc., serve to control operating magnets, as 6 and 5, associated with indicators, as 905 and 904, which are mounted on shafts, as 593A and 508B, driven by shafts 502 and 503 respectively. These shafts are positioned by the recording relays in groups N and N! respectively, when relay 52! is operated.

A more detailed description of the structure covered by the present invention will now be given. In Fig. 1 is disclosed a receiving distributor A controlled over the line circuit 810 by a sending distributor at a master station (not shown). The distributor A, which is provided with an outer ring having segments 1-8 and an inner ring having segments 804 and 805, is mounted on a shaft 11, driven by the usual motor (not shown) in synchronism with the sending distributor. Also mounted on shaft 11 is a brush 800, which when rotated is adapted to form a connection between the outer and the inner rings. Of the two inner ring segments, 805 corresponds in length to segments 2 and 3 of the outer ring and segment 804 is equal in length to the remaining segments 4-8 inclusive. A magnet 802, provided with a latch 801, serves to release the brush 800 for rotation and to stop its rotation at the end of a revolution. A line circuit 810, connected to the master station, extends in series through the winding of a neutral relay 806 and the windings of a polar relay 807. The neutral relay 806, when energized, serves to connect ground to the segment 804 of the inner ring, while the polar relay 807, when energized, serves to connect either positive or negative potential to the segment 805 of the inner ring.

Likewise mounted on shaft 11 are timing cams 12 and 30. Cam 12 is provided with a reentrant portion 16, while co-operating with the cam is a grounded follower 15A, which moves between its two contacts 13 and 14. When shaft 11 is in its normal position, the follower 15A is positioned in the reentrant portion 16 of the cam 12, and, consequently, as it then rests against contact 14, applies ground to conductor 62. When, however, shaft 11 moves from its normal position, the follower 15A rests on the periphery of cam 12, thus closing contact 13 and grounding conductor 66. The effect of grounding conductors 66 and 62 will be explained later. Cam 30 is provided with a reentrant portion which extends over $\frac{1}{8}$ of the circumference of the cam. Co-operating with the cam is a follower 101B which controls contacts 31 and 101. During the first three-eighths of a revolution of shaft 11, the follower 101 is in the reentrant portion of the cam 30, and during this period contacts 101 and 31 are closed, 101 grounding conductor 101A and 31 placing the ground connection on conductor 32 under control of relay 103; while for

the remainder of the revolution of shaft 11, the follower 101B rides on the periphery of cam 30, opening these contacts. The effect of grounding these conductors will be mentioned later.

Associated with segments 2 and 3 of the outer ring on distributor A are polar nominating relays 15 and 18, respectively. These relays are designed, in a manner well known in the art, so that when de-energized, their armatures remain on the contact to which they were last moved. When relay 15 is energized by positive potential, its armature is moved against contact 16, and when energized by negative potential, it is moved against contact 17. In a similar manner, the armature of relay 18 is moved against contact 41 when energized by positive potential, and against contact 42 when energized by negative potential.

Controlled by the polar nominating relays 15 and 18 are the subsidiary relays 43, 44, 45, 46 and 103. Relays 43 and 45 are energized when polar relay 15 closes its contacts 16 and 17 respectively. Relays 44 and 46 are energized when polar relay 18 closes its contacts 41 and 42 respectively. The operation of relays 44 and 45 serves to energize relay 103, which prevents cam 30 from grounding conductor 32 and also serves to ground conductor 32A. The operation of relays 43 and 46 serves to ground conductor 202. The operation of relays 45 and 46 serves to ground conductor 109. The operation of relays 43 and 44 serves to ground conductor 102. The effect of grounding the conductors mentioned will be explained hereinafter.

Referring to Figs. 3, 4 and 5, relay 27 is a combined stock and shelf group relay, relay 47 is a quantity, and relay 701 is a price group relay. Associated with the combined stock and shelf group relay 27 are single letter odd stock control relays 23 and 28, single letter even stock control relays 24 and 29, and shelf control relays 51 and 52. Associated with single letter odd control relays 23 and 28 is a group of relays K, comprising a transfer relay 69 and four recording relays 37, 38, 39 and 40. Similarly, group of relays K!, comprising transfer relay 234 and four recording relays 79-82, is associated with single letter even control relays 24 and 29; group of relays L, comprising a transfer relay 245 and four recording relays 234-237, is associated with shelf control relays 51 and 52; while groups of relays M, M1, M2, N, N1, N2 and N3, each likewise comprising a transfer relay and four recording relays, are associated, respectively, with ten thousands quantity control relays 53 and 54, thousands quantity control relays 55 and 56, hundreds quantity control relays 57 and 58, hundreds price control relays 709 and 721, tens price control relays 710 and 722, units price control relays 711 and 723, and fractions price control relays 712 and 724.

During the selecting operation, as will be explained later, the previously operated control relays are released, pair by pair, in a predetermined sequence, beginning with the single letter odd control relays 23 and 28, and continuing through the succeeding pairs of relays in consecutive order, reading from left to right on Figs. 2, 3 and 4. The control relays in the upper horizontal row, such as 23, 24, etc., will be termed master control relays and those in the lower horizontal row, as 28, 29, etc., will be termed mate control relays. The master control relays, except the first one in the stock, quantity and price control relay groups, and the shelf master

control relay are provided with locking windings controlled by mate control relays of the preceding control relay pair. For example, mate control relay 721 of price group of control relays is adapted, when operated, to energize the holding windings of master control relays 710, 711 and 712. Adapted to be operated by either of the mate control relays 28 or 29, is shelf guard relay 74; adapted to be operated by either shelf guard relay 74 or mate control relay 52 is quantity guard relay 77; adapted to be operated by either quantity guard relay 77 or the mate control relays 54, 56 or 58 is price guard relay 213; and adapted to be operated by either price guard relay 213 or the mate control relays 721—724 is recording guard relay 738. Shelf guard relay 74, when energized, serves to lock shelf master relay 51 and to cause the energization of quantity guard relay 77. Relay 77, when energized, serves to lock the master quantity control relays 53, 55 and 57 and to cause the energization of price guard relay 213. Relay 213, when energized, serves to lock the master price control relays 709—712 and to cause the energization of recording guard relay 738. The function of relay 738 will be explained later.

Upon the release of the shelf guard relay 74, the shelf control relays 51 and 52 are conditioned for release when conductors 62 and 66 are opened; upon the release of the quantity guard relay 77, the quantity control relays 53—58 are conditioned for release, pair by pair, as they are placed under control of conductors 62 and 66 by mate relays 54, 56 and 58. Upon the release of price guard relay 213, the price control relays 709—712 and 721—724 are conditioned for release, pair by pair, as they are placed under control of conductors 62 and 66 by mate relays 721—724. The release of mate relay 724 de-energizes recording guard relay 738 for a purpose to be explained later.

The guard relays, therefore, condition the groups of control relays, that is, the shelf control relay, the quantity control relay group, and the price control relay group, for release, group by group, in a predetermined order, while the mate relays within a particular group of control relays condition the control relays in that group for release, pair by pair, and the last mate relay within any group releases the guard relay associated with the succeeding control relay group, thus conditioning the control relays in that group for release, pair by pair. It is evident from the arrangement of the guard relays in a chain circuit that, if the shelf control relays and the quantity control relays remain unoperated, the price guard relay 213 will nevertheless be operated to lock price control relays 709 and 721 during the stock selecting operation. Other advantages and functions of the chain guard relay will be apparent from the subsequent description.

The transfer relay associated with any group of relays, as K, serves, when operated by the release of the associated master control relay, as 23, while the mate relay, as 28, remains operated, to connect the recording relays, as 37, 38, 39 and 40, to segments 4, 5, 6 and 7 of the distributor A. Each of the recording relays, as 37, 38, etc., is then adapted to be selectively operated from segments 4, 5, 6 and 7 of the distributor, and when operated, to lock to guard conductor 249A which was grounded by guard relay 738, whose operation was described above. When the mate relay, as 28, associated with a transfer relay, as 68, releases, the transfer relay

also releases, grounding circuits controlled by the locked recording relays, as 37, 38, etc. The effect of these circuits will be described later.

In Fig. 5 is disclosed a pair of stock selectors O and O₁; in Figs. 6 and 7, a number of multiple bank selector switches P—P₅; and in Fig. 7, a system of shafting for positioning the indicators of Fig. 10. A motor 914 is adapted to drive shaft 327 continuously through shaft 349, gears 913 and 913A, and friction clutch 328, and to drive shaft 348 continuously through shaft 349, gears 913 and 913B, and friction clutch 350. Shaft 327 is arranged to drive, through suitable gearing shaft 318 of stock selector O, shaft 346 of selector switch P and shaft 347 of selector switch P₁. Shaft 348 is arranged to drive, through suitable gearing shaft 323 of stock selector O₁, shaft 911 of selector switch P₂, shaft 915 of selector switch P₃, shaft 916 of selector switch P₄, and shaft 917 of selector switch P₅.

The extent of movement of shafts 318, 346 and 347 is determined by stock selector O, while the extent of movement of shafts 323, 911, 915, 916 and 917 is determined by stock selector O₁.

These stock selectors O and O₁ are ordinary code selectors of a type well known in the printing telegraph art. Only such parts are shown as are necessary to an understanding of the operation of these selectors in the present system. For a complete description of these selectors reference may be made to United States Patent No. 1,639,213 to F. G. Creed.

The parts of the stock selectors are shown in a detached arrangement in order to simplify the description. It is to be understood, however, that the parts shown and the other necessary parts may be assembled to form a unitary structure. The stock selectors are constructed on a four unit basis with four code discs, as 301—304, each corresponding to one of the recording relays in the several groups, as 37—40 in group K, and likewise corresponding to one of the distributor segments 4—7. Referring to stock selector O, the four code discs 301—304 are provided with central bores that permit them to be freely mounted on the shaft 318. The shaft serves as a common bearing for the code discs 301—304, and the magnets, as 337 and 338, associated with code discs 301 acting through a pivoted armature attached to the code disc 301, serve to rock that disc in one direction or the other on shaft 318. Similar magnets, associated with each of the other code discs, perform the same function. The magnets 337—340 serve to return their associated code discs to normal or zero position, while the remaining magnets 339, 341—343 serve to rock their associated discs to a predetermined position with reference to shaft 318.

The peripheries of the code discs 301—304 are predeterminedly notched in a manner well known in the printing telegraph art. Arranged transversely with respect to the slots in the code discs are sixteen transverse members 305, 306, etc. By operating the code discs singly or in varying combinations, the peripheral slots can be aligned in sixteen different ways, and whenever the slots are aligned under any one of the sixteen transverse members, that member is moved into the path of an arm 307. Arm 307 is attached to cam 324 which is in turn mounted on shaft 318. One of the transverse members 305 is a normal positioning member and is moved into the path of arm 307 when the restoring magnets 337—340 have been operated to restore the code discs 301—304 to their normal or zero position.

Since the engagement of arm 307 with a transverse member, as 305, 306, etc., frees the friction clutch 328, through which shafts 327 and 318 are driven by motor 914, the shaft 327 can be stopped at any one of fifteen operating positions and a normal position by variably operating the code discs 301—304 to position predetermined transverse members in the path of arm 307. It is to be noted that the operation of the code discs to 10 position a predetermined transverse member in the path of arm 307 causes the transverse members previously in the path of that arm to be withdrawn.

The stock selector O₁ is similar in construction 15 to the stock selector O. It is provided with four code discs 314—317, restoring magnets 347—349, and operating magnets 361—364, respectively associated with these discs. When operated by operating magnets 361—364 the code discs 314—20 317 are adapted to position any one of sixteen transverse members 361, 363, etc. in the path of arm 362. This arm is attached to cam 333 which in turn is mounted on shaft 323. In the case of stock selector O₁, the engagement of the arm 362 25 with a transverse member frees the friction clutch 350 through which shafts 348 and 323 are driven by motor 914, and hence the shaft 348 can be stopped at any one of the fifteen operating positions and a normal position corresponding to the engagement of arm 362 with transverse member 361. It is, therefore, evident that, by variably 30 operating stock selector O, shaft 327, and hence shaft 346, of selector switch P and shaft 347 of selector switch P₁, can be stopped at a normal position and fifteen operating positions, and that by variably operating stock selector O₁, shaft 348, and hence shafts 911, 915—917 of selector switches P—P₅ respectively, can be stopped at a normal position and fifteen operating positions. The stock selectors O and O₁ thus serve to position the wipers mounted on the shafts of selector switches P—P₅ upon predetermined contacts in their associated contact banks.

Associated with the stock selectors O and O₁ 45 are two relays 310 and 313. Relay 310, when operated, serves to connect circuits 334, 412, 413, etc., controlled by the recording relays in groups K₁, M—M₂ and N—N₃, to the selector switch P. Now the contacts of switch P, as 308Z, 308M, etc., 50 are connected by conductors, as 1 and 4, to magnets, as 1 and 4, associated respectively with indicators 900 and 904 (Fig. 10) for displaying quotations relating to the single letter odd stock Q. The function of relay 310, therefore, is to extend the circuits from the recording relays in the shelf, quantity and price groups to the single letter odd selector switch P, from which such circuits are extended by conductors, as 1—11, to the magnets associated with the indicators of a single letter odd stock, as Q. Relay 313, when operated, 55 serves to connect circuits 334, 412, 413, etc., controlled by the recording relays in groups K₁, M—M₂ and N—N₃, to the selector switch P₂. The contacts of switches P₂ are connected by 60 conductors, as 12—22, to the magnets 12—22 associated with the indicators of the single letter even stock A. The function of relay 313, therefore, is to extend the circuits controlled by the recording relays in the shelf, quantity and price 65 groups to the magnets associated with the indicators of the single letter odd stock, as Q₁. When neither relay 310 nor relay 313 is operated, the circuits, as 334, 412, 413, etc., controlled by the recording relays in groups K₁, M—M₂ and N—N₃ 70 are connected to the transfer selector switch P₁.

Through transfer switch P₁ these circuits can be connected to any of the selector switches, such as P₃, P₄, P₅, etc. If the circuits are connected to selector switch P₃, the operation of that switch will connect the circuits controlled by the previously mentioned recording relays through conductors, as 23—33, to magnets 23—33 associated with a two letter stock in the first group, as Q. Similarly, if the circuits are connected to selector switches P₄, the operation of that switch will 10 connect circuits through conductors, as 34—44, to the magnets 34—44 associated with the indicators of a two letter stock of the second group, as Q₃. When neither relay 310 nor 313 is energized, therefore, the circuits controlled by the 15 recording relays of the shelf, quantity and price groups are extended to the operating magnets associated with the indicators of a two letter stock.

Rigidly mounted on shaft 318 is a cam 324 20 having a reentrant portion, as shown, into which a follower 325A is arranged to move when the shaft 318, and consequently the cam, is in its normal position. When the stock selector O is operated, permitting rotation of shaft 318, the follower 324A moves out of the reentrant portion of the cam and on to the periphery of the cam, thus closing a circuit for energizing relay 310.

Similarly, a cam 333 rigidly mounted on shaft 323 is provided with a follower 333A which is 30 moved out of a reentrant portion of the cam and on to its periphery, when stock selector O₁ is operated, allowing movement of shaft 323. While the cam follower is on the periphery of the cam, a circuit is closed for operating relay 313. When 35 both shafts 318 and 323 are rotated by the operation of stock selectors O and O₁, the cam followers 325A and 333A serve to hold both relays 310 and 313 de-energized. It is thus evident that the operation of stock selector O causes relay 310 40 to be operated, and the circuits 334, 412, 413, etc. to be connected to selector switch P for a single letter odd stock selection; that the operation of stock selector O₁ causes relay 313 to be operated, and the circuits 334, 412, 413, etc. to be connected to selector switch P₂ for a single letter 45 even stock selection; and that the operation of stock selectors O and O₁ causes relays 310 and 313 to be held de-energized and the circuits 334, 412, 413, etc. to be connected to transfer selector 50 switch P₁ for a two letter stock selection.

Also rigidly mounted on shaft 318 is a ratchet wheel 319, which serves when shaft 318 is rotated to close an operating circuit for a slow-release relay 321. Similarly, a ratchet 347, which is rigidly mounted on shaft 323, serves to close an operating circuit for a slow-release 321A. Relay 321, when energized, prevents the movement of code discs 301—304 while shaft 318 is being rotated, and relay 321A, when energized, prevents the movement of code discs 314—317 while shaft 323 is being rotated, thus ensuring the selection of the proper stock upon the operation of the stock selectors O and O₁.

Referring to Fig. 10, there are shown schematically the indicators for displaying quotations and a number of stocks, as Q, Q₁, Q₂ and Q₃. Any suitable construction of the indicator may be used, for example, a structure such as that illustrated in my Patent 1,967,331, issued July 24, 70 1934. Although the indicators for displaying quotations on four stocks are alone illustrated in the drawings, it is to be understood that in actual practice additional indicators would be supplied to display quotations on a larger number of 75

stocks. For reasons that will be explained later, stock Q is termed a single letter odd stock; Q1, a single letter even stock; Q2, a two letter stock of the first group; and Q3, a two letter stock of the second group.

Each stock, as Q, is provided with a group of indicators comprising twenty price indicators and three quantity indicators. The twenty price indicators of each stock, as Q, are divided into five sub-groups or shelves, each containing four indicators, as 900, 901, 902 and 903, which are adapted to display respectively the fractions, units, tens and hundreds digits of the price. The indicators of the several sub-groups or shelves, as 910, 909, 908 and 900-903, serve to display respectively the previous close, open, high, low and current price quotations on the stock Q. The three quantity indicators 904, 905 and 906 serve to indicate, respectively, the hundreds, thousands and ten thousands digits of the last quantity quotation on stock Q.

One set of shafts 508-508F serves to position the groups of indicators for stocks Q and Q2, and another set of shafts 508G-508M serves to position the groups of indicators for stocks Q1 and Q3. Corresponding indicators in the indicator groups for stocks Q and Q2, that is, indicators which display the same digit in the price or quantity, are mounted on the same shaft. Similarly, corresponding indicators in the indicator groups for stocks Q1 and Q3 are mounted on the same shaft. For example, indicator 906 which serves to display the ten thousands quantity digit of stock Q, and indicator 531 which serves to display the ten thousands quantity digit of stock Q2, are mounted on the ten thousands quantity shaft 508. Similarly, thousands quantity indicators 905 and 531A of stocks Q and Q2 are mounted on the thousands quantity shaft 508A, hundreds quantity indicators 904 and 540 of stocks Q and Q2 are mounted on hundreds quantity shaft 508B, hundreds price indicators, as 903 and 530, of stocks Q and Q2, respectively, are mounted on hundreds price shaft 508C, tens price indicators, as 902 and 530B, of stocks Q and Q2, respectively, are mounted on tens price shaft 508D, units price indicators, as 901 and 530C, of stocks Q and Q2, respectively, are mounted on units price shaft 508E, and fractions price indicators, as 900 and 530D, of stocks Q and Q2, respectively, are mounted on fractions price shaft 508F. In a like manner, the ten thousands, thousands and hundreds quantity indicators of stocks Q1 and Q3 are mounted, respectively, on ten thousands quantity shaft 508G, thousands quantity shaft 508H, and hundreds quantity shaft 508I; while the hundreds, ten, units and fractions price indicators of stocks Q1 and Q3 are mounted, respectively, on hundreds price shaft 508J, tens price shaft 508K, units price shaft 508L, and fractions price shaft 508M.

The ten thousands quantity shafts 508 and 508E are arranged to be driven by the common ten thousands quantity shaft 501; the thousands quantity shafts 508A and 508H, by the common thousands quantity shaft 502; the hundreds quantity shafts 508B and 508I, by the common hundreds quantity shaft 503; the hundreds price shafts 508C and 508J, by the common hundreds price shaft 504; the tens price shafts 508D and 508K, by the common tens price shaft 505; the units price shafts 508E and 508L, by the common units price shaft 506; and the fractions price shafts 508F and 508M, by the common fractions price shaft 507.

The common shafts 501-507 inclusive are arranged to be driven by motor 914 through shaft 349, suitable gearing 509, and friction clutches, as 526 and 529, individual to each of the shafts 501-507.

The extent of movement of any of the shafts 501-507 is controlled by means of code selectors similar to the stock selectors O and O1 of Fig. 5. On each of the shafts 501-507, as on the ten thousands quantity shaft 501, there are mounted four code discs 955, 955A, 955B and 955C, with which are respectively associated magnets 525, 525A, 525B and 524A. By energizing the magnets singly or in various combinations, the associated code discs will be so positioned that any predetermined one of sixteen transverse members (not shown) may be extended into the path of an arm (not shown) of shaft 501. When the shaft 501 is rotated by motor 914, the predetermined transverse member and the arm come into engagement, with the result that the friction clutch 526 is then freed and the shaft 501 is set to a predetermined position. Hence the ten thousands quantity shafts 508 and 508G, whereon the ten thousands quantity indicators 906 and 331, and 906A and 531B are mounted and which are driven by shaft 501, are positioned in accordance with the setting of the code discs 955-955C. In a similar manner the shafts 502-507, and the shafts driven thereby, may be set to predetermined positions in accordance with the setting of the code discs associated with the several shafts. Each code disc, as 955, is provided with a spring, as 955, which serves, when the associated magnet, as 525, is de-energized, to restore the code disc to its normal or zero position. When all of the code discs, as 955-955C, associated with the same shaft, as 501, have thus been restored to their normal or zero positions, a transverse member (not shown) is positioned in the path of the arm (not shown) on the shafts, as 501, and the shaft is thus restrained from further movement.

With the indicators 900, 901, 902 and 903 on the current shelf of stock Q are associated, respectively, the operating magnets 1, 2, 3 and 4. Similarly associated with the indicators in the last quantity shelf are the operating magnets 5, 6 and 7. Operating magnets 8, 9, 10 and 11 are common, respectively, to the indicators on the low, high, open and previous close shelves. In a similar manner, the indicators of other stock groups, as Q1, Q2 and Q3, are provided with associated operating magnets, such magnets being individual to the indicators in the current price shelf and on the last quantity shelf, and common to the indicators on the remaining shelves, as described in connection with stock Q. When the shaft on which a given indicator is mounted has been set to a predetermined position, as explained above, and the operating magnet individual to that indicator is energized, the indicator is set to a position in accordance with the position of the shaft. Likewise, when the magnet common to the indicators on a particular shelf is energized, the indicators are thereupon set to the position of the shafts on which they are severally mounted. For a complete disclosure of the means and method of positioning these indicators in accordance with the position of the shafts on which they are severally mounted, reference may be made to applicant's co-pending application for an Automatic stock quotation display board, Serial No. 382,268, filed July 30, 1929 and to the above mentioned patent.

Referring to Figs. 6 and 7, five selector switches P—P5 are shown, although it is to be understood that in actual practice twelve additional selector switches would be employed in stock selection. It will be remembered that when relay 310 (Fig. 5) is operated, circuits, such as 344, 412, etc., controlled by the recording relays of groups L—N3, are extended to switch P; when relay 313 is operated, these circuits are extended to switch 10 P2; and when neither relay 310 nor 313 is operated, these circuits are extended to switch P1. The function of selector switch P is to extend these circuits to the several operating magnets, as 1—11, associated with the indicators, as 15 900—910, of a predetermined single letter odd stock, as Q; the function of switch P2 is to extend these circuits to the several operating magnets, as 12—22, associated with the indicators, as 20 900A—910A of a predetermined single letter even stock, as Q1; and the function of switch P1 is to transfer these circuits to one of the 25 switches, such as P3, which in turn extends them to the several operating magnets, as 23—33, associated with the indicators, as 530—530E, 531—531A, 540, 30A—33A, of a predetermined two letter stock, as Q2.

Each of the switches, as P, is provided with eleven contact banks, as 308A, 308B, etc., and a common bank, as 308P, associated with each of the 30 contact banks. Each of the contact banks contains seventeen contacts, as 308Z, 308R, etc., and corresponding contacts in the several banks, as contacts 308Z, 308M, 308L, etc., in banks 308A, 308D and 308X, respectively, of switch P, are arranged in vertical rows. There are thus seventeen vertical rows of contacts in the contact banks of each switch, but two of these rows are inactive. In switches P, P2—P5, the eleven contacts in each of the active vertical rows are connected to the operating magnets associated with the indicators of a particular stock. For example, contacts 308Z, 308M, 308L, etc., in the second vertical row of switch P, are connected by conductors 1—11 to the operating magnets 1—11 associated with the indicators 900—910 of single letter odd stock Q; the contacts in the second vertical row of switch P2 are connected by conductors 12—22 to the operating magnets 12—22 associated with the indicators 900A—910A of a single letter even stock Q1; the contacts in the second vertical row of switch P3 are connected by conductors 23—33 to the operating magnets 23—33 associated with the indicators of the two letter stock Q2; and the contacts in the second vertical row of switch P4 are connected by conductors 34—44 to the operating magnets 34—44 associated with the indicators of the two letter stock Q3.

Each one of the eleven contacts in any active vertical row in switch P1 is connected to a closed bank associated with one of the eleven contact banks of switches P3, P4, P5, etc. For example, contact 354 in bank 309A of switch P1 is connected by conductor 318A to common bank 312A of switch P3; contact 254B is connected by conductor 318B to common bank 312C of switch P4; and contact 354C is connected by conductor 318C to common bank 312D of switch P5.

Associated with each contact bank and common bank, as 308A and 308P of switch P, is a double-ended wiper, as 308, which serves to connect the common bank and the contacts in the contact bank, and which normally rests on two dead contacts. The wipers of switch P are mounted on a common shaft 346; the wipers of

switch P1 are mounted on a common shaft 347; while the wipers of switches P2—P5 are mounted on common shafts 911, 915—917, respectively. Shafts 346 of switch P and shaft 347 of switch P1 are adapted to be driven through suitable gearing by shaft 327, whose movement, as previously described, is determined by stock selector O. Shaft 911 of switch P2, shaft 915 of switch P3, shaft 916 of switch P4, and shaft 917 of switch P5 are adapted to be driven through suitable gearing by shaft 347 whose movement is controlled by stock selector O1. It is to be noted that the arm 307 of stock selector O may make one revolution while the wipers of switches P and P1 are making a half revolution, and that the 15 arm 362 of stock selector O1 may move similarly with respect to the wipers of switches P2—P5. This relation between the movement of arms 307 and 362 and the wipers of switches P—P5 may be obtained by providing reduction gearing between 20 shafts 327 and shafts 346 and 347 of switches P and P1, and between shafts 348 and shafts 911, 915, 917 of switches P2—P5.

From the foregoing description it is apparent that through switch P fifteen single letter odd stocks can be selected, through switch P2 fifteen single letter even stocks can be selected, and through switch P1 and switches P3, P4, P5, etc., two hundred and twenty-five two letter stocks can be selected. The present system, as shown, 30 is therefore capable of selecting any one of two hundred and fifty-five stocks. It is to be understood, however, the applicant is not to be limited to this precise number, for by providing additional segments on the receiving distributor A, 35 additional recording relays, additional code discs, and additional contacts on the selector switches as well as additional switches, the present system can be extended to permit selection of a much larger number of different stocks.

The operation of the above-described system will now be described in some detail. In describing the operation it will be assumed that the indicators on the previous close shelf Pc of all the stocks Q, Q1, Q2 and Q3 have been set to display the last quotation of the previous day and that the indicators on the remaining shelves O, H, L, etc., of those stocks have been set to blank. It will be assumed further that the quotation to be posted pertains to the stock Q2, 50 that the quantity of shares sold is 99,000, that the price of the sale is 123½, and that this price is to be indicated or displayed on the open, high, low and last price shelves of stock Q2.

In order to post the quotations described, the first operations include three nominating operations, the first involving the selection of the price group relay 701, the second, the selection of the quantity group relay 47, and the third, the selection of the combined stock and shelf group relay 60 21. The group relays are nominated or selected in the order named because, in posting some quotations, it is necessary to select only the quantity group relay and the price group relay, or only the price group relay alone, and in such cases, 65 unless the price group relay were normally selected first and the quantity group relay normally selected next, it would be necessary to provide means for making the selections for these relays ineffective on the combined stock and shelf group 70 relay 27.

It seems desirable to point out here the two cases: where it would be necessary to select only the quantity group relay 47 and the price group relay 701, and where it would be necessary to se- 75

lect only the price group relay 701. The present system is designed to maintain a stock selection once set up until a new stock selection is made. Hence, in the case where a succession of quotations on the same stock are to be posted, the posting of the quotations following the first one posted will not require the selection of the stock and shelf group relay 27. If any of such succeeding quotations requires that the ten thousands 5 quantity indicator be positioned, however, the quantity group relay 47 and the price group relay will be selected. But if any quotation requires that either or both the thousands and hundreds 10 quantity indicators be positioned, and not the ten 15 thousands quantity indicator, and either or both the units and fractions price indicators be positioned, and not the tens or hundreds price indicators, only the price group relay 701 will be selected. These operations will be described in 20 more detail hereinafter, but they are mentioned here in order to explain the reason for selecting the group relays in the above-mentioned order.

In describing the operations required to post the abovementioned quotation, it will be assumed 25 that at the master station (not shown) suitable means are provided, in a manner well known in the printing telegraph art, to transmit impulses over the line circuit to effect the operation of the apparatus disclosed in Figs. 1-10 inclusive. The 30 first of every series of impulses transmitted will be a starting impulse which causes relay 806 to energize, thereby grounding segment 804 of the inner ring, and through the brush 800 causing the magnet 802 to energize over an obvious circuit. Upon energizing, this magnet attracts the 35 latch 801, allowing shaft 11, and consequently brush 800, to be driven by the synchronized motor (not shown). The starting impulse also energizes polar relay 807, but as the brush 800 does not rest 40 on either segments 2 or 3 of the outer ring of the distributor, the energization of that relay is without effect at this time. At the end of each revolution of the brush 800, the transmitting means at the master station (not shown) opens the line circuit 45 810, de-energizing the magnet 802 and causing its latch 801 to stop the brush 800. If another starting impulse is transmitted when the brush reaches segment 1 of the outer ring, this magnet is re-energized, its latch attracted, and the brush 50 allowed to rotate for another revolution. The operations of the relay 806 in grounding the segment 804 of the inner ring, while the brush is rotating over the segments 4, 5, 6 or 7 of the outer ring, and the operation of the polar relay 807 in moving its armature 808 to either position in 55 response to received impulses to place positive or negative battery on the segment 805 of the inner ring, while the brush 800 is rotating over segments 2 and 3, are similar in every case. Consequently, 60 for the sake of brevity, the description of the operation will make no mention of the starting and stopping of the brush 800, and will proceed on the assumption that either positive or negative potential is placed on segments 2 and 3 of the outer distributor ring and that ground is placed 65 on segments 4, 5, 6 or 7 of the same ring, as required.

Prior to the reception of impulses from the master station, shaft 11 on which the distributor 70 A is mounted is in its stop or normal position, and hence the follower 101B is resting in the re-entrant portion of the cam 30 so that conductors 101A and 32, as previously mentioned, are grounded. Price group relay 701 is therefore operated over a circuit extending from battery, 75

armature 702 of guard relay 738, winding of relay 701, conductor 101A, to ground on contacts 101 at cam 30. When price group relay 701 pulls up, the price control relays 709-712 are associated through contacts 704-707 with segments 4-7 of 5 the outer distributor ring, and ground is connected through contacts 708 to guard lead 62 for a purpose to be explained later. The grounding of conductor 32 is without effect at this time because the operating circuit 745 of quantity 10 group relay 47 is open at contacts 741 of guard relay 738 and the operating circuit 744A of stock and shelf group relay 27 is open at contacts 740 of relay 738.

Price group relay 701 is held energized while 15 the brush 800 is making $\frac{3}{8}$ of a revolution, that is, until it has passed over segments 2 and 3 of the outer ring, by means of the cam 30, since for that period the follower 101B rests on the reentrant portion of the cam, with the result, as previously 20 explained, that conductor 101A is connected to ground during that time.

Negative potential on segment 2 operates nominating polar relay 15 over conductor 15B, causing that relay to close its contacts 17, and positive potential on segment 3 operates nominating polar relay 18 over conductor 18C, causing that relay to close its contacts 41. The closure of contacts 17 operates subsidiary relay 45 and the closure of contacts 41 operates subsidiary relay 30 44 over obvious circuits. The operation of relay 45 closes a locking circuit for price group relay 701, which may be traced from ground, contacts 201 of relay 46, contact 200 of relay 45, conductor 32A, contacts 703 of price group relay 701 (which 35 are closed because at this time the brush 800, being on segment 2 of the outer ring, has not made $\frac{3}{8}$ of a revolution), winding of relay 701 to battery. The operation of relay 44 completes an operating circuit for relay 103 which may be 40 traced from battery, winding of relay 103, contacts 104 of relay 45, contacts 204 of relay 44 to ground. Relay 103 thereupon energizes, opening its contacts 105, thereby removing ground from conductor 32 to prevent the energization of 45 the stock and shelf group relay 27 and the quantity group relay 47 over that conductor, when guard relay 738 is subsequently energized.

As the price 123 $\frac{1}{2}$ comprises three integers and a fraction, segments 4, 5, 6 and 7 of the outer 50 ring are grounded. Master price control relays 709, 710, 711 and 712 are therefore energized and locked. Relay 712 energizes over a circuit from battery, winding of relay 712, contacts 704 of price group relay 701, conductor 19 to ground on 55 segment 4 of the distributor ring; relay 711 energizes over a circuit from battery, winding of relay 711, contacts 705 of price group relay 701, conductor 20 to ground on segment 5 of the distributor ring; relay 710 energizes over a circuit from battery, winding of relay 710, contacts 706 60 of price group relay 701, conductor 21 to ground on segment 6 of the distributor ring, and relay 709 energizes over a circuit from battery, winding of relay 709, contacts 707 of price group relay 65 701, conductor 22 to ground on segment 7 of the distributor ring. The relays 709-712 lock over obvious circuits to ground on guard lead 62 which, as previously mentioned, was grounded by the closure of contacts 708 of price group relay 701. 70

The operation of master price control relay 709 causes its associated mate relay 721 to energize over a circuit from battery, winding of relay 721, to ground on contacts 717 of relay 709. Likewise the operation of the master control 75

relays 710, 711 and 712 causes the operation of their associated mate relays 722, 723 and 724 over similar circuits.

Upon operating, the price control relays 721—5 724 complete obvious locking circuits to conductor 66 which is now grounded at contacts 13 by cam 12, in the manner previously described, since that cam is now in its off-normal position. However, these locking circuits are unnecessary to hold 10 the relays 721—724 operated at this time, for so long as price group relay 701 remains operated, conductor 62 will be grounded, and as price control relays 709—712 are locked to this conductor, they and consequently mate relays 721—724 can—15 not release.

When price control relay 724 operates, it completes, at its contacts 737, an obvious circuit for operating guard relay 738. This relay, upon energizing, at its contacts 739 grounds conductor 20 743 which serves, as will be explained later, as a locking conductor for the operated recording relays, and for the change-over relay 99 and also causes the operation of wipe-out relays 93 25 and 94 whose functions will be described later; at its contacts 740 and 741 connects one terminal of the winding of stock and shelf group relay 21 and the quantity group relay 47, respectively, to battery, but as the other terminals of these windings have been opened by the operation of relay 30 103, the closure of these contacts is without effect; at its contacts 742 places conductor 752 under control of the group of subsidiary relays 44—46 for a purpose to be explained later, and by attracting armature 702 opens the previously 35 traced operating circuit of price group relay 701, but that relay still remains energized over its locking circuit 32A.

The operation of price control relay 723 completes at its contacts 736A an obvious locking circuit for price control relay 712, and at its contacts 736, an obvious locking circuit for guard relay 738. Similarly, the operation of price control relay 722 completes obvious locking circuits for price control relays 711 and 712, and a locking circuit for guard relay 738, and the operation of price control relay 721 completes obvious locking circuits for price control relays 710, 711 and 712 and a locking circuit for guard relay 738. This system of interlocking circuits, as previously 50 mentioned, is for the purpose of allowing the operated price control relays 709—712 and 721—724 to be subsequently released, pair by pair, and to prevent a price control relay, as 711, from being released prematurely and in the wrong 55 sequence, if the preceding price control relay, as 710, is not energized, while a price control relay, as 709, preceding the last-mentioned control relay 710, is energized. In that case, it is obvious that control relay 721, which is operated when 60 709 operates, would hold relay 711 locked until both 709 and 721 had been released.

One revolution of shaft 11 and the brush 800 has now been completed. Cam 12 therefore 65 allows contacts 14 to close, grounding conductor 62, but as this conductor is also grounded at contacts 708 of price group relay 701, the price control relays 709—712 are not now dependent upon the closure of contacts 14. Cam 30 allows contacts 101 to close grounding conductor 101A, 70 which is connected to one terminal of the operating winding of price group relay 701, but as conductor 702A connected to the other terminal has been opened by guard relay 738, the operating winding of the price group relay 701 remains 75 de-energized though the locking relay remains

closed to ground over conductor 32A. Cam 30 also allows contacts 31 to close, but as relay 103 is still energized, conductor 32 common to the quantity group relay 47 and the stock and shelf group relay 27 remains open.

On the second revolution of the brush 800, the quantity group relay 47, the quantity control relays 53 and 55, and mate relays 54 and 56 are to be energized. Positive potential on segment 2 and negative potential on segment 3 of the distributor ring energize nominating relays 15 and 18 respectively, causing relay 15 to close its contacts 16 and relay 18 to close its contacts 42. The operation of relay 15 causes relay 45 to release and relay 43 to energize, while the operation of relay 18 causes relay 44 to release and relay 46 to energize. The release of relay 45 opens at its contacts 104 the circuit of relay 103, and at its contacts 200 the circuit for locking price group relay 701, which circuits have previously been traced. Relays 701 and 103 then release. Upon the release of relay 103, the quantity group relay 47 operates over a circuit extending from battery, contacts 741 of guard relay 738, contacts 218 of price guard relay 213, 25 operating winding of relay 47, conductor 32, contacts 31 of cam 30 (which are still closed since the brush 800 is on segment 2), to ground on the armature of relay 103, and stock and shelf group relay 27 operates over a circuit from battery, contacts 740 of guard relay 738, contacts 288 of shelf guard relay 74, operating winding of relay 27, conductor 32 to the previously mentioned ground.

Group relay 27, which operates about the same 35 time that relay 701 releases at its contacts 25 grounds guard conductor 62, thus preventing the release of price control relays 709—712 upon the release of price group relay 701, and at its remaining contacts associates the stock control relays 23 and 24 and the shelf control relay 51 with segments 4, 5 and 6 of the distributor ring. Group relay 47, upon operating, at its contacts 212 likewise grounds guard conductor 62, and at its remaining contacts, associates quantity control relays 53, 55 and 57 with segments 4, 5 and 6 of the distributor ring.

To return to the operation of the subsidiary relays, the energization of relay 43 is without effect. The energization of relay 46 completes a 50 locking circuit for quantity group relay 47 that may be traced from battery, locking winding of relay 47, locking contacts 219, contacts 205 of relay 46, contacts 206 of relay 45, to ground on contacts 207 of relay 46. Over this circuit, group relay 47 will be held energized for the remainder of the second revolution of the brush 800. After the brush has left segment 3 of the distributor ring, cam 30 removes ground from conductor 32, thus releasing group relay 27 which has not been 60 locked, but having no effect upon group relay 47 whose locking circuit has been closed by the operation of subsidiary relay 46. The quantity control relays 53, 55 and 57 are now the only control relays associated with segments 4, 5 and 6 65 of the distributor ring.

The quantity to be displayed represents 99,000 shares and, therefore, segments 4 and 5 of the distributor ring are grounded, thus causing the operation of control relays 53 and 55. Relay 53 70 is operated over a circuit from battery, winding of relay 53, contacts 211 of relay 47, conductor 19 to ground on segment 4, and relay 55 is operated over a circuit from battery, winding of relay 55, contacts 208 of relay 47, conductor 20 to 75

ground on segment 5. Relays 53 and 55 lock over an obvious circuit to ground on guard conductor 62 which is now grounded by relay 47. Control relays 54 and 56 are operated over obvious circuits upon the operation of relays 53 and 55 respectively, and lock to ground on conductor 66 which is now grounded by cam 12 through contacts 13. These relays are not now controlled by cam 12, however, as their associated control relays 53 and 55 are locked to conductor 62. Relay 54, upon operating, completes an obvious locking circuit for relay 55 an operating circuit for price control relay 213 and an alternative locking circuit for guard relay 750. This last-mentioned circuit may be traced from battery, winding of relay 750, conductor 108 to ground on contacts 216 of relay 54. Relay 55, upon operating, completes obvious locking circuits for guard relay 213 and relay 750.

20 The energization of relay 750 prevents the energization of the changeover relay 99 and the shift relay 521, whose functions will be described in detail later, as long as any one of the quantity control relays 54, 56 and 58 is energized. The 25 system of interlocking circuits permits the release of the quantity control relays, pair by pair, in their proper sequence, while the energization of the price guard relay 213 closes obvious locking circuits for the price control relays 789—712 and for the guard relay 738, thus preventing the release of these last-mentioned relays until all of the relays, such as 54, 56 and 58 in the quantity control group have been released. The energization of price guard relay 213 also opens at 35 its contacts 218 the operating winding of group relay 47, but that relay is held energized by its locking winding.

The second revolution of the brush 800 has been completed and on the third revolution the 40 stock and shelf group relay 27 is to be operated and predetermined stock and shelf control relays are to be selected.

When the brush has completed the second revolution, the cam 12, being in its normal position, grounds conductor 62 and removes ground from conductor 66. However, this is not material for, as previously mentioned, conductor 62 is now grounded by relay 47, and hence none of the control relays is yet under control of cam 50 12. Also cam 30, since relay 103 is de-energized, grounds both conductors 101A and 32. The grounding of conductor 101A, as previously noted, is without effect on price group relay 701, while the grounding of conductor 32, though is without effect on the operating winding of relay 47 whose circuit is open at contacts 218 of price guard relay 213, does, however, operate group relay 27 over a circuit previously traced. The operation of relay 27, at its contacts 25 grounds conductor 62 to hold operated the control relays, as 53 and 55, when group relay 47 subsequently releases, and at its remaining contacts associates stock control relays 23 and 24 and shelf control relay 51 with segments 4, 5 and 6 of the distributor ring.

Negative potential on segments 2 and 3 during the third revolution of brush 800 causes relay 15 to energize, closing its contacts 15, and relay 18 to energize, closing its contacts 42.

70 The relay 15, upon operating, closes its contacts 17 thus energizing relay 45, and relay 18, upon operating, closes its contacts 42 thus energizing relay 46. The opening of contacts 16 of relay 15 releases relay 43, but this is without effect as no circuits were closed through the con-

tacts of this relay. The operation of relays 45 and 46 completes a locking circuit for stock and shelf group relay 27 which may be traced from battery, winding of relay 27, locking contacts 224 of relay 27, conductor 109, contacts 223 of relay 45, contacts 207 of relay 46 to ground. The operation of relay 45 at its contacts 206 opens the previously traced locking circuit for quantity group relay 47, and since the operating winding of this relay is open at contacts 218 of price 10 guard relay 213 the quantity group relay releases.

As the quotation is to be posted for a two letter stock, and is to be posted on more than the last quotation shelf, the stock control relays 23 and 24 and the shelf control relay 51 are to be operated, and hence segments 4, 5 and 6 of the distributor ring are grounded. Relay 23 energizes over a circuit from battery, winding of relay 23, contacts 26 of relay 27, conductor 19 to ground on segment 4; relay 24 energizes over a circuit from 20 battery, winding of relay 24, contacts 226 of relay 27, conductor 20 to ground on segment 5, and relay 51 energizes over a circuit from battery, winding of relay 51, contact 225 of relay 27, conductor 21 to ground on segment 6 of the distributor. These relays are locked over obvious circuits to guard conductor 62, which is grounded through contacts 25 of relay 27, while their associated control relays 28, 29 and 52 operate over obvious circuits and lock to conductor 66 which is now grounded by the action of cam 12 which is in its off-normal position. The operation of relay 28 completes a locking circuit for relay 24 independent of conductor 62 and an operating circuit for shelf guard relay 74; the operation of relay 29 completes an alternative operating circuit for guard relay 74, while the operation of guard relay 74 completes an obvious locking circuit for shelf control relay 51, an operating circuit for quantity guard relay 77, and opens at its contacts 288 40 the operating circuit of shelf and stock group relay 27 without affecting that relay, however, since its locking winding is closed. Relay 77 pulls up, closing additional locking circuits for quantity control relays 53, 55 and 57, thus holding the quantity control relays against release until the control relays in the stock and shelf control relays have been released.

The wipers of the stock selecting switches P, P1, P2, etc. rest on the contacts corresponding to the stock last selected on the previous day. It is, therefore, necessary to reset the stock selectors O and O1 to their zero or normal positions and thus restore the switch wipers to their normal positions prior to the selection of a new stock. To effect this, relay 23, upon operating, causes the energization of relays 337—340 of stock selector O, thus restoring the code discs 301—304 to their normal positions, and relay 24, upon operating, causes the energization of relays 347—350 55 of stock selector O1, thus restoring the code discs 314—317 to their normal positions. Relays 337—340 are energized over common conductor 344, contacts 91 of relay 89 to ground on contacts 111 of relay 23. Relays 347—350 are energized over common conductor 345, contacts 92 of relay 89 to ground on contacts 113 of relay 24. Thus the transverse members previously in the path of arms 307 and 362 are withdrawn; transverse members 305 and 361 are moved into the path of the arms mentioned, thereby allowing motor 914 to drive shafts 318 and 323 until they are stopped by transverse members 305 and 361. In this way code discs 301—304 and code discs 314—317 are set to their normal positions. When shafts 318 75

and 323 are moved to their normal positions, as described, the shafts 346, 347, 911, 915-917 are likewise moved to the same position under control of the stock selectors O and O1, thus positioning 5 the wipers of switches P-P5 on their normal or rest contacts.

In the previous operations, the nominating operations or the selections of the group relays began with the selection of the price group relay 10 191 and ended with the selection of the stock and shelf group relay 27. The operations now to be described, or the selecting operations, begin with the recording relay group K associated with the stock and shelf group relay 27 and end with 15 the recording relay group N3 associated with the price group relay 701. The stock Q2, as previously mentioned, is to be selected.

Negative potential on segment 2 energizes nominating relay 15, which retains its contacts 20 17 closed, and positive potential on segment 3 energizes nominating relay 18, which opens its contacts 42 and closes its contacts 41. The opening of contacts 42 releases relay 46 which, at its contacts 207 opens the previously traced locking 25 circuit of group relay 27. As the operating circuit of relay 27 was previously opened by the operation of shelf guard relay 74, relay 27 thereupon releases, at its contacts 25 removing ground from conductor 62, and at its contacts 225, 226 30 and 26 opening the operating circuits of relays 23, 24 and 51, thereby placing the first pair of stock control relays 23 and 28 under control of cam 12. The other control relays are locked by the system of interlocking circuits before described and hence will not now be released by the action of cam 12. The operation of relays 44 and 45 energizes relay 103 over a circuit previously traced, thus causing ground to be removed from conductor 32 to which the operating windings of group relays 27 and 47 are connected. As 40 the price group relay 701 has its operating circuit opened at the contacts of guard relay 738, it is evident that none of the group relays 27, 47 or 701 will be operated during the selecting operation.

45 It will be assumed that, to make the proper stock selection, code disc 301 of stock selector O and code disc 314 of stock selector O1 are to be operated. When, in the next or fourth revolution of brush 800, the cam 12 moves off-normal, contacts 14 are opened, removing ground from conductor 62, thereby releasing stock control relay 23, and contacts 13 are closed, grounding conductor 66, thereby maintaining a locking circuit 50 for relay 28. Upon the release of relay 23 transfer relay 69 and guard relay 89 are energized, the former over a circuit from ground on contacts 67 of relay 23, contacts 68 of relay 28, winding of relay 69 to battery, and the latter over a circuit 55 from the same ground and through contacts 63 of relay 28, winding of relay 89 to battery. Upon operating, slow-release relay 89 opens contacts 91 and 92, preventing the energization of the restoring magnets 337-350 of stock selector O when contacts 116 of relay 23 are grounded by 60 the release of that relay and contacts 85 of relay 24 are closed, and preventing the energization of the restoring magnets 347-350 of stock selector O1 through grounded contacts 113 of relay 24 and conductor 114. Relay 89 does not release 65 but is re-energized, as will be explained later, when relay 24 is released. The operation of transfer relay 69 associates the recording relays 37-40 with segments 4, 5, 6 and 7 of the distributor ring.

70 As code disc 301 of stock selector O is to be positioned, ground is on segment 4 thereby energizing recording relay 37 over the following circuit, battery, winding of relay 37, contacts 36, conductor 19 to ground on segment 4. Relay 37 locks through contacts 78, conductor 231A to conductor 743, which, as previously explained, was grounded by the operation of guard relay 738. When the brush 800 of the distributor A reaches the end of its fourth revolution, the cam 12 causes 75 contacts 13 to open, removing ground from conductor 66, thereby releasing the relay 28. The release of relay 28 opens at its contacts 63 the previously traced circuits for guard relay 89 and transfer relay 69; opens at its contacts 70 the locking circuit for relay 24, which is now held locked to conductor 62, since the cam 12 is in its normal position; and at its contacts 72 opens one of the alternative operating circuits for shelf guard relay 74, which is now held up by relay 29. The release of relay 28, therefore, places relay 24 under control of cam 12. Relay 69 releases, but relay 89, being slow-releasing, does not. Upon the release of transfer relay 69, positioning relay 330 of stock selector O operates over a circuit from battery, winding of relay 330, conductor 88, contacts 83 of relay 37, contacts 84 of relay 69, conductor 84A, contacts 322 of slow-release relay 321 to ground. The operation of relay 330 causes the code disc 301 to be rocked by 30 pivoted armature 330A, thus aligning the slots in the discs 301-304 under the transverse member 306, thereby moving that transverse member into the path of arm 307 and withdrawing the transverse member 305 from the path of that arm. The continuously operable motor 914 then drives 35 shaft 327 through friction clutch 328 until the shaft 318 is stopped by the engagement of arm 307 with transverse member 306. The wipers of stock selector switches P and P1, which are mounted on shafts 346 and 347 driven by shaft 327, are thus brought to rest on the first contacts in their associated banks, as 308Z and 308M of switch P and contact 254 of switch P1. When stock selector O is operated, follower 325A co-operating with cam 324 causes the energization of relay 310 over the following circuit, battery, winding of relay 310, contacts 325 to ground on contacts 332. The operation of relay 310 connects the circuits, as 334, 412, 413, etc. which are controlled by the recording relays of the shelf, quantity and price groups, through contacts, as 351, 415, etc. of relay 310, to the common banks 308P, 308Q, etc. of selector switch P. These circuits are now open, however, and their connection to switch P is at 40 this time without effect.

45 On the next or fifth revolution of the brush 800, the cam 12, upon being moved off-normal, opens contacts 14, removing ground from conductor 62 to which relay 24 is locked, thereby releasing that relay, and closes contacts 13, grounding conductor 66 to which relay 29 is locked, thereby preventing the release of this relay. The release of relay 24 energizes transfer relay 234 and re-energizes guard relay 89; the latter being 50 energized over a circuit from battery, winding of relay 89, contacts 90 of relay 29 to ground on contacts 87 of relay 24, and the former being energized over a circuit from battery, winding of relay 234, contacts 90 of relay 29 to ground on contacts 70 87 of relay 24. The retention of relay 89 in its operated condition holds contacts 91 and 92 open, thus preventing the operation of the restoring relays 336-240 and 347-350 of stock selector O and O1; while the operation of the transfer relay 75

234 associates the recording relays 79—82 of group K1 with segments 4, 5, 6 and 7 of the distributor.

As code selector 314 of stock selector O1 is to be operated, ground is on segment 4, thereby operating recording relay 79 over the following circuit, battery, winding of recording relay 79, conductor 19 to ground on segment 4 of the distributor ring. Relay 79 locks to ground on conductor 743 through contacts 235B of relay 79, and conductor 249A.

When the brush 800 has completed the fifth revolution, cam 12 causes contacts 13 to open and contacts 14 to close. The opening of contacts 13 removes ground from conductor 66, thus releasing relay 29 which was locked to this conductor. The release of relay 29 opens at its contacts 90 the previously traced circuits of the guard relay 89 and the transfer relay 234. After an interval guard relay 89 releases, closing contacts 91 and 92, but as both relays 23 and 24 are now de-energized, the circuits of the restoring magnets 337—340 and 337—350 are now open. The release of the transfer relay 234 disassociates the recording relays 79—82 from segments 4, 5, 6 and 7 of the distributor ring. The release of relay 29, at its contacts 13, also opens the circuit of shelf guard relay 74. This guard relay thereupon releases, opening at its contacts 75 both the locking circuit for shelf control relay 51, which is now held locked by grounded guard conductor 62, and an alternative operating circuit for quantity guard relay 71, which is held operated by relay 52, and at its contacts 288 closing one side of the operating circuit of stock and shelf group relay 21. The next pair of control relays 51 and 52 are thus placed under control of cam 12.

Upon the release of transfer relay 234 a circuit is completed for operating positioning relay 361 associated with code disc 314 of stock selector O1. This circuit may be traced from battery, winding of relay 361, contacts 238 of relay 79, contacts 237 of relay 234 to ground on contacts 365 of slow-releasing relay 321A. Upon the operation of relay 361, code disc 314 is rocked, allowing transverse member 363 to be drawn into the path of the arm 362 and the transverse member 361 withdrawn. This results in shaft 348 being driven by motor 914 through friction clutch 350, until shaft 323 of stock selector O1 is stopped by the engagement of the arm 363 with transverse member 362. As a result of this movement of shaft 323 and hence of shaft 348, shafts 911, 915—917 on which the wipers of switches P2—P5 are mounted, are rotated until these wipers are brought to rest on the first active contacts in their associated banks.

It is to be noted that when shaft 318 is being rotated, slow-release relay 321 is intermittently energized by a grounded spring 320 which is actuated by ratchet wheel 319. Similarly, while shaft 323 is being rotated slow-release relay 321A is intermittently energized by grounded spring 356 which is actuated by ratchet wheel 347. When the relays 321 and 321A are energized, they prevent the closure of the operating circuits of the positioning magnets 330—343 and 361—364 of stock selectors O and O1 until the shafts 318 and 323 have completed their movements.

Upon the operation of stock selector O1, relay 310 is de-energized by the opening of contacts 332 by cam 333 co-operating with follower 333A, while relay 313 remains unoperated, since its operating circuit is open at contacts 326 controlled by cam 324. As relays 310 and 313 are both de-

energized, the circuits previously traced to switch P are disconnected from that switch and connected to the common banks of switch P1.

Before tracing the circuits through the operated selector switches P—P5, the operation of the system in carrying out the remainder of the selection will be described. It is evident from the foregoing description of the selection of the recording relays in groups K and K1 that on the sixth revolution of the distributor brush 800 shelf 10 recording relays 246, 247 and 248; on the seventh revolution tens thousands quantity recording relays 286 and 287; on the eighth revolution thousands quantity recording relays 287 and 288; on the ninth revolution hundreds price recording relay 133; on the tenth revolution tens price recording relay 131; on the eleventh revolution units price recording relay 132; and on the twelfth revolution fractions price recording relay 133 can be selected, and that the selected recording relays will be locked to conductor 743 grounded by guard relay 138.

It is also evident that when shelf control relay 52 is released, the quantity guard relay 77 will be de-energized, thereby placing the first pair of quantity control relays 53 and 54 under control of cam 12; that after relay 54 is released, the next operated pair, as 55 and 56, are placed under control of cam 12; that when the last operated pair of control relays in the quantity group is released, guard relay 750 is released and also price guard relay 213, which closes at its contacts 218 one side of the operating circuit of group relay 47 and places the first pair of control relays 709 and 721 in the price group under control of cam 12; that the interlocking circuits permit the release of the price control relay by the cam 12, pair by pair; and that upon the release of the last pair of price control relays, guard relay 733 is released, removing the ground at its contacts 739 from guard conductor 743, closing one side of the operating circuit of the group relay 701, and opening its remaining contacts for a purpose to be later described.

It will be recalled that the wipers of the switches P—P5 rest on the first active contacts in their associated banks, and that both relays 310 and 313 are de-energized. When, therefore, transfer relay 245 releases after shelf recording 50 relays 246, 247 and 248 have been operated, circuits are completed for energizing the operating magnet 32 associated with the indicators 32A on the open shelf of stock Q2, the operating magnet 31 associated with the indicators 31A on the high shelf, and operating magnet 30 associated with the indicators 30A on the low shelf. The circuit for operating magnet 32 may be traced from ground on contacts 250 of transfer relay 245, contacts 254 of relay 246, conductor 366, contacts 368 of relay 313, contacts 372 of relay 310, conductor 375, wiper 378 of switch P1, conductor 381, wiper 387 of switch P3, contact 390A, conductor 32 (the designation of a conductor corresponds to that of the operating magnet in Fig. 10, to the winding of which the designated conductor is connected) to winding of operating magnet 32 and battery; the circuit for operating magnet 31 may be traced from ground on contacts 250 of transfer relay 245, contacts 255 of relay 247, conductor 367, contacts 370 of relay 313, contacts 373 of relay 310, conductor 376, wiper 378 of switch P1, conductor 382, wiper 388 of switch P3, contact 391A, conductor 391, conductor 31, winding of 75

magnet 31 to battery; and the circuit for operating magnet 30 may be traced from ground on contacts 250 of transfer relay 245, contacts 258 of relay 248, conductor 368, contacts 371 of relay 5 313, contacts 374 of relay 310, conductor 377, wiper 380 of switch P1, conductor 383, wiper 389 of switch P3, contact 392A, conductor 392, conductor 30, winding of magnet 30 to battery. The part played by the operating magnets on position 10 the indicators in the associated shelves will be described later.

When the transfer relay 261 is released after the ten thousands quantity recording relays 266 and 267 have been operated, circuits are completed for energizing the operating magnet 29 associated with the ten thousands quantity indicator 531 of stock Q2, and the magnets 525 and 524A associated respectively with code discs 955 and 955C, which serve to control the movement 20 of the ten thousands quantity shaft 501. Magnet 29 is operated over a circuit from ground on contacts 276 of transfer relay 261, contacts 275 of relay 266, contacts 271 of relay 267, conductor 273, contacts 396 of relay 313, contacts 397 of 25 relay 310, conductor 398, wiper 399 of switch P1, conductor 406, wiper 401 of switch P3, conductor 403, conductor 29, winding of magnet 29 to battery. Magnet 525 is energized over a circuit from ground on contacts 276 of transfer relay 30 261, contacts 270 of relay 267, conductor 278, winding of magnet 525 to battery; magnet 524A is energized over a circuit from ground on contacts 276 of transfer relay 261, contacts 274 of 35 relay 266, conductor 277, winding of magnet 524A to battery. The operation of magnet 525 rocks the code disc 955 and the operation of magnet 524A rocks the code disc 955C, in the manner described in connection with Fig. 5, so that the ninth transverse member is permitted to be 40 drawn into the path of an arm (not shown) on shaft 501, and the normal stop transverse member withdrawn from the path of this arm, whereupon the motor 914 through gears as 509 and friction clutch 526 drives shaft 501 until the 45 arm mentioned engages the ninth transverse member (not shown), upon which the rotation of the shaft 501 is stopped by the slipping of the friction clutch 526. Shafts 508 and 508G driven by shaft 501 are rotated to a similar position. As 50 operating magnet 29 has been energized, the ten thousands indicator 531 of stock Q2 is alone positioned to display the digit 9. For a detailed description of the manner in which the indicator 531 is set to the position of the shaft 508, 55 reference should be made to the co-pending application mentioned above.

When the transfer relay 282 is released and the thousands quantity recording relays 287 and 288 are energized, circuits are completed for energizing operating magnet 28 associated with the thousands indicator 531A of stock Q2, and to operate magnet 528 associated with code disc 594 and magnet 527 associated with code disc 954C, both of which discs control the movement of the 60 thousands quantity shaft 502. The circuit for operating magnet 28 may be traced from ground on contacts 298 of transfer relay 282, contacts 291 of relay 287, contacts 294 of relay 288, conductor 295, contacts 405 of relay 313, contacts 70 406 of relay 310, conductor 407, wiper 408 of switch P1, conductor 409, wiper 410 of switch P3, conductor 412, conductor 28, winding of magnet 28 to battery; the circuit for operating magnet 528 may be traced from ground on contacts 75 298 of transfer relay 282, contacts 293 of relay

288, conductor 297, winding of magnet 528 to battery; and the circuit for operating magnet 527 may be traced from ground on contacts 298 of transfer relay 282, contacts 292 of relay 287, conductor 296, winding of magnet 527 to battery. 5 Similarly to the operation of magnets 525 and 527 associated with code discs 955 and 955C respectively of shaft 501, the operation of magnets 528 and 527 cause their associated code discs 954 and 954C to permit the thousands quantity shaft 10 502 to be rotated to the ninth position, at which it is stopped by the ninth transverse member engaging an arm on shaft 502. Shafts 508A and 508H, on which the thousands quantity indicators, as 905 and 531A are mounted, are therefore rotated to the same position as shaft 501. As the operating magnet 28 has been energized, the thousands indicator 531A is set to a position corresponding to the position of shaft 508A, and when so positioned displays the digit 9. Since 20 the ten thousands indicator 531 displays the digit 9 and the thousands indicator 531 also displays the digit 9, the quantity quotation of 99,000 shares has thus been set up.

It is to be remembered at this point that the 25 quantity control relays 57 and 58 were not operated. These relays serve to associate the recording relays, as 287A, with the distributor A for selection to effect the operation of a magnet, as 30 27, associated with a hundreds quantity indicator, as 540 of a particular stock, as Q2. However in the present case, as the quantity to be posted is 99,000 and indicator 540 has been previously set to zero, it is unnecessary to re-position 35 that indicator in order to display the proper quantity. Consequently, when control relay 56 released price guard relay 213 was then released, placing the first pair of price control relays 109 and 721 under control of cam 12.

When transfer relay 730B releases and the 40 hundreds price recording relay 730 is operated, circuits are completed for energizing operating magnet 26 associated with the hundreds price indicator 530 of stock Q2, and the magnet 533 associated with the code disc 952C which serves with 45 other discs to control the movement of the hundreds price shaft 504. The circuit for energizing magnet 26 may be traced from ground connected to the contacts of transfer relay 730B, contacts 735E of relay 730, conductor 142, contacts 105 of 50 changeover relay 99, conductor 413, contacts 414 of relay 313, contacts 415 of relay 310, conductor 416, wiper 417 of switch P1, conductor 418A, wiper 419 of switch P3, conductor 421, conductor 26, winding of magnet 26 to battery; and the circuit for operating magnet 533 may be traced from ground on contacts of transfer relay 730B, contacts 734K of relay 730, conductor 141, contacts 532 of shift relay 521, winding of magnet 533 to battery. The operation of magnet 533 55 positions the associated code disc 952C, thus permitting, in the manner previously described, the hundreds price shaft 504, to be moved to the first position, and the shafts 508C and 508J, on which the hundreds price indicators are mounted, to be set to a corresponding position by motor 914. As magnet 26, associated with hundreds price indicator 530 of stock Q2, is operated and the magnets 30, 31, and 32 are also operated, the current hundreds price indicator 530 and the 60 hundreds price indicators on the open, low and high shelves are set to the position of shaft 508C, that is, are set to display the digit 1 which represents the hundreds digit of the price to be posted—123½.

When the transfer relay 755 is released and the tens price recording relay 731 is operated, circuits are completed for energizing operating magnet 25 associated with tens price indicator 530B of stock Q2, and for energizing magnet 523C associated with code disc 951B which with other code discs controls the movement of tens price shaft 505. The circuit for operating magnet 25 may be traced from ground on contacts 760 of transfer relay 755, contacts 737K of relay 731, conductor 765, contacts 102 of changeover relay 99, conductor 412, contacts 414A of relay 313, contacts 415A of relay 310, conductor 415B, wiper 417A of switch P1, wiper 419A of switch P3, conductor 25, winding of magnet 25 to battery; and the circuit for operating magnet 523C may be traced from ground on contacts 760 of transfer relay 755, contacts 736K of relay 731, conductor 765B, contacts 539 of shift relay 52, winding of magnet 523C to battery. In the manner described above, the operation of magnet 523C causes tens price shaft 505 and shafts 508D and 508K, on which the tens price indicators are mounted, to be set to the second position. As magnet 25 associated with tens indicator 530B of stock Q2 and magnets 30, 31 and 32 are operated, the indicator 530B on the current price shelf and the tens indicator on the open, high and low shelves of stock Q2 are set to the position of shaft 508D, that is, they are set so that they display the digit 2.

When the transfer relay 732 B is released and units price recording relay 732 is operated, circuits are completed for operating magnet 519A associated with code disc 950 A, which with other code discs controls the movement of units price shaft 506, and for energizing operating magnet 24 associated with units price indicator 530C of stock Q2. The circuit for operating magnet 24 may be traced from ground on the contacts of transfer relay 732B, contacts 738 of relay 732, conductor 739, conductor 334, contacts 354 of relay 313, contacts 352A of relay 310, wiper 417B of switch P1, wiper 419B of switch P3, conductor 24, winding of magnet 24 to battery; and the circuit for operating magnet 519A may be traced from ground on contacts of transfer relay 732B, contacts 733 of relay 732, conductor 793, winding of magnet 519A to battery. The operation of magnet 519A, in the manner described above, causes the units price shaft 506 and the shafts 508E and 508L, on which the units indicators are mounted, to be set to the third position by the motor 914 and then stopped. As the operating magnet 24 associated with units price indicator 530C of stock Q2 and the operating magnets 30, 31 and 32 are energized, the units price indicator 530C on the current price shelf and the units price indicator on the high, open and low shelves of stock Q2 are set to the position of shaft 508E, that is, are set to display the numeral 3.

When the transfer relay 771 is released and fractions price recording relay 733 is energized, circuits are completed for energizing the operating magnet 23 associated with fractions indicator 530E of stock Q2 and for operating magnet 515C associated with code disc 514, which with other code discs controls the movement of fractions price shaft 507. The circuit for operating magnet 23 may be traced from ground on contacts of transfer relay 771, contacts 741 of relay 733, conductor 798, conductor 334A, contacts 351A of relay 313, contacts 353 of relay 310, conductor 334A, wiper 309 of switch P1, conductor 318A, wiper 312 of switch P3, conductor 23, winding of magnet 23 to battery; and the circuit for oper-

ating magnet 515C may be traced from ground on the contacts of transfer relay 771, contacts 740 of relay 733, conductor 795, winding of magnet 515C to battery. The operation of magnet 515C permits shaft 507 to be rotated by motor 914, in the manner described above, until that shaft and shafts 508F and 508M on which the fractions indicators are mounted are positioned at the fourth position. As operating magnet 23 associated with fractions indicators 530E is operated and as operating magnets 30, 31 and 32 are also operated, the fractions indicator 530E of the current price shelf and the fractions indicators on the open, high and low shelves will be positioned in accordance with the position of shaft 508F, that is, these indicators will be positioned to display the fraction $\frac{1}{2}$. The price $123\frac{1}{2}$ is, therefore, displayed on the current price shelf and on the open, high and low shelves of stock Q2.

Certain additional operations that occur will now be explained. When fractions price control relay 724 is released, guard relay 738 is de-energized. At its outermost contacts this relay, in releasing, reconnects battery over conductor 702A to one terminal of the operating winding of price group relay 701; at its contacts 742, disconnects conductor 102 from conductor 752A, thus opening another break in the operating circuit of the changeover relay 99 and the shift relay 521; at its contacts 741, disconnects battery from one terminal of the operating winding of group relay 47; at its contacts 740, disconnects battery from one terminal of the operating winding of group relay 27; and at its contacts 739 removes ground from guard conductor 743 to which the recording relays are locked. However, an alternative source of ground is connected to guard conductor 249A to insure that the recording relays will not release before the shafts, as 501—507, have been set to their predetermined positions. Associated with each of the shafts 501—507 is a ratchet wheel 517. A spring 518 is actuated by each of these ratchets, whenever the shaft on which the ratchet wheel is mounted is in motion, and this spring serves to close a contact 518A in the circuit of a slow-release magnet 519. The operation of any ratchet wheel, therefore, closes the circuit of magnet 519. This magnet, upon energizing, connects ground through its contacts 520 to the guard conductor 249A holding the recording relays locked. The positive positioning of all of the shafts 501—507 is thus insured.

When, finally, ground is removed from guard conductor 249A, upon the shafts 501—507 coming to rest, the circuits of wipe-out relays 93 and 94 are opened. Relay 93 releases immediately, but relay 94, being slow-releasing, holds up for an interval. The operated recording relays also release and the spring associated with the operated code discs return those discs to their normal positions, thus allowing the shafts 501—507 to be driven by motor 914 to their normal positions. At the same time the operating magnets 29 and 28, associated with indicators 531 and 531A of stock Q2, are operated over circuits extending from ground on contacts of relay 96, and through contacts 95 and 93 of slow-release relay 94, to conductors 273 and 295 of the magnets 29 and 28 respectively, and thence over the circuit previously traced to operate these magnets. As the shafts 508 and 508A are restored to normal, the operation of magnets 29 and 28 causes the ten thousands quantity indicator 531 and the thousands quantity indicator 531A to be released to their zero positions. All required circuits are

now restored to normal, with the switches P1 and P3 connecting the circuits controlled by the shelf, quantity and price recording relays in connection with the operating magnets of stock Q2, and the stock selectors O and O1 remaining in the position last set.

Let it be assumed that the next sale is for 9,000 shares of the same stock at 123 1/2, which is a new low.

10. The first operation consists in nominating the fraction price control relay 701. Shaft 11 is in its normal stopped position, and therefore cam 30 permits contacts 31 and 101 to close, the closure of the former grounding conductor 32 and the closure of the latter grounding conductor 101A. As one terminal of the operating winding of group relay 27 is open at contacts 740 of guard relay 738 and one terminal of the operating winding of group relay 47 is open at contacts 741 of guard relay 738, the grounding of conductor 32 is ineffective. The grounding of conductor 101A, however, energizes price group relay 701 over a circuit previously traced.

Negative potential on segment 2 and positive potential on segment 3 of the distributor ring energize nominating relay 15, which closes its contacts 17, and nominating relay 18, which closes its contacts 41. Relay 15 causes subsidiary relay 45 to operate and relay 18 causes subsidiary relay 44 to operate over obvious circuits. The energization of relays 44 and 45 closes a previously traced circuit for relay 103, which thereupon operates, preventing, in the manner previously described, the operation of group relays 21 and 47.

35. The energization of relay 44 is ineffective in completing a holding circuit for any of the group relays, but the energization of relay 45 grounds conductor 32A, as before described, locking price group relay 701.

40. As the fractions price control relays are alone to be operated, since only the fraction of the price has changed, ground on segment 4 of the distributor ring operates fraction control relay 712 over a circuit from battery, winding of relay 712, contacts 704 of relay 781, conductor 19 to ground on segment 4. Relay 712, upon operating, locks to ground on conductor 62, which was grounded by the operation of relay 701, and causes the associated control relay 724 to operate over a circuit previously traced, and lock to guard conductor 66, which is grounded by cam 12 which is now in its off-normal position. Upon the operation of control relay 724, guard relay 738 is energized, thereby conditioning the group relays 27 and 47 for operation, in the manner above described, opening the operating winding of group relay 701, and grounding the guard conductor 743. However, as the locking circuit of group relay 701 is closed, this relay remains operated.

50. At the end of the first revolution of the brush 800, cam 12 causes conductor 62 to be grounded and conductor 66 to be opened. Therefore, control relay 712, which is also grounded by guard relay 701, is held locked and this in turn holds relay 724 locked.

The second operation involves the nomination of the thousands quantity control relays, and this will be effected upon the second revolution of the brush 800. Positive potential on segment 2 and negative potential on segment 3 of the distributor ring cause nominating relay 15 to close its contacts 16 and nominating relay 18 to close its contacts 42; the closure of the former causing relay 45 to release, thereby de-energizing relay 103, and relay 43 to energize, and the closure of

the latter causing relay 44 to release and relay 46 to energize. The release of relay 103 permits cam 30 to ground conductor 32, thus giving group relays 27 and 47 an initial energization. The de-energization of relay 45 opens at its contacts 200 the locking circuit of group relay 701, which releases. The energization of relay 43 is without effect and the energization of relay 46 grounds at its contacts 205 the locking circuit 202 of quantity group relay 47. As group relay 27 is not nominated, that is, as no locking circuit is prepared for it by the operation of the subsidiary relays it is released by cam 30.

As the quantity to be posted is 9,000 shares, the quantity control relay 55 is to be operated, and hence ground is on segment 3 of the distributor ring. Control relay 55 is therefore energized over the circuit previously traced, locking to conductor 62, grounded by group relay 47, and the associated control relay 56 is likewise operated and is held up by relay 55. The operation of relay 56 operates price guard relay 213 over an obvious circuit, and this guard relay locks fractions control relay 712 and guard relay 738 over obvious circuits. The operation of relay 213 opens at its contacts 218 the operating circuit of group relay 47.

The third operation involves the nomination of the shelf control relays, which is accomplished on the third revolution of the brush 800. It is to be remembered that the price involves a new low quotation. When the brush 800 reached its normal position group relay 27 was alone given an initial energization, since the operating circuits of group relays 47 and 701 had been opened. As described above, negative potential on segment 2 and negative potential on segment 3 nominates or completes a locking circuit 109 for group relay 27, opening the locking circuit of group relay 47, which releases. Ground on segment 6 of the distributor ring then causes the energization of control relay 51 over a circuit previously traced, and that relay in turn causes the energization of its associated control relay 52. Relay 51 locks to guard conductor 62, which is now grounded by group relay 27, and as the relay 51 is locked its associated relay 52 is held against release.

The selecting operations now take place, that is, the selection of predetermined recording relays in the groups L, M1 and N3 associated with the operated control relays 51, 52, 55, 56 and 712, 713 respectively.

It is evident from the detailed description given in connection with the portion of the opening quotation that the low shelf recording relay 248 in group L, the recording relays 287 and 288 in group M1, and the recording relay 776 in group N3 can be selectively operated by the distributor A. As the wipers of the stock selector switches P1 and P3 rest on the contacts in their associated banks to which they were set by the last selection, the operation of relay 248, after transfer relay 245 releases, completes circuits for energizing the operating magnet 38 associated with the indicators on the low shelf of stock Q2. These circuits have been previously traced. Likewise, when the transfer relay 282 is released and the recording relays 287 and 288 are energized, circuits are completed for energizing the operating magnet 28, associated with the thousands quantity indicator 531A of stock Q2, and to operate the magnets 527 and 528 associated with the code discs 954C and 954. As previously described, the operation of these magnets causes the thousands indicator 531A of stock Q2 to be positioned to display the digit 9. Furthermore, when the transfer relay 771 is released 75

- and the recording relay 716 is operated, circuits are completed for energizing the operating magnet 23 associated with the fractions indicator 530E of stock Q2, and for operating the magnet 515B 5 associated with code disc 513 mounted on the fractions shaft 507. The operation of these magnets causes the fractions indicator 530E to be positioned, in the manner described above, to display the fraction $\frac{1}{8}$, and the fractions indicator 30A, on 10 the low shelf whose associated operating magnet 30 is energized, to display the same fraction. It is thus evident that the quantity indicators display 99 which represents 9,000 shares, and the last price shelf and the low shelf display 123 $\frac{1}{2}$, which was 15 the price to be posted.
- It is obvious from the foregoing that a price change in the fraction of a quotation on the same stock, which quotation is not a new high or low, could be posted by merely selecting the group 20 relay 701, and operating predetermined recording relays in group N3, thereby changing only the fraction indicator 530E on the last shelf of stock Q2.
- The present system is designed, as mentioned 25 above, to permit the posting of a quotation involving either or both the thousands and hundreds indicators of the quantity and not the ten thousands indicator, and either or both the units and fractions indicators of the price and not the hundreds and tens indicators by nominating only the price group relay 701. Assume that a quotation on stock Q2 is now to be posted, consisting of 900 shares and the price 123 $\frac{1}{2}$, which differs from the posted price 123 $\frac{1}{2}$ only in the fraction.
- Upon the first revolution of the distributor brush 800 the price group relay 701 is nominated and the control relays 710 and 722, and control relays 712 and 724 are energized in the manner described above.
- During the second revolution of the distributor brush 800 positive potential is on segments 2 and 3 of the distributor ring, and nominating relay 15 is operated to close its contacts 16 and nominating relay 18 is operated to close its contacts 41.
- The closure of contacts 16 energizes relay 43, and the closure of contacts 41 energizes relay 44. A circuit is therefore completed for energizing changeover relay 99 and shift relay 521. Relay 99 energizes over a circuit from battery, winding of relay 99, conductor 752, and relay 521 energizes over a circuit from battery, winding of relay 521, conductor 752, and both circuits continue through contacts 751 of relay 750 (which is unoperated since none of the quantity control relays is energized), contacts 742 of energized guard relay 738, conductor 102, contacts 203 of relay 43, contacts 294 of relay 44 to ground. Upon the operation of the changeover relay 99, the conductor 742 controlled by the recording relays of the hundreds price group N, which was connected to the operating magnet 26 associated with the hundreds indicator 530 on the last shelf of stock Q2, is now transferred through contacts 103 of changeover relay 99 into connection with conductor 295, which is connected, over a circuit previously traced, with the operating magnet 26 associated with the thousands quantity indicator 531A of stock Q2; conductor 765 controlled by the tens price recording relays of group N1, which was connected to the operating magnet 25 associated with the tens indicator 530B on the last shelf of stock Q2, is now transferred through contacts 100 of changeover relay 99 into connection with conductor 422 which is in connection, over a circuit previously traced, 75 with the operating magnet 27 associated with the
- hundreds quantity indicator 540 of stock Q2. Upon the operation of shift relay 521 the conductors 747, 961, 962 and 963, controlled by the recording relays of the hundreds price group N, which formerly were in connection with magnets 533A, 533B, 533C, 533 which control the code discs mounted on the hundreds price shaft 503, are connected through 534A, 535A, 536A, 532A to the magnets 528, 528A, 528B and 527 associated with the code discs mounted on the thousands quantity 10 shaft 502; the conductors 765A, 765B, 766B and 766 controlled by the recording relays of the tens price group N1, which were formerly in connection with magnets 523A, 523B, 523C and 523 associated with the code discs on the tens price shaft 15 503, are connected through contacts as 538A of relay 521 to magnets 570, 570A, 570B and 524 associated with the code discs mounted on the hundreds quantity shaft 503.
- In the remainder of the second revolution, recording relays 753 and 754 are energized and locked. Upon the release of transfer relay 755 with 20 753 and 754 energized, a circuit is completed for operating magnets 570 and 524 associated with code discs 953 and 953C respectively, which with 25 other code discs controls the movement of the hundreds quantity shaft 503, and for energizing operating magnet 27 associated with the hundreds quantity indicator 540 of stock Q2. The circuit for operating magnet 27 may be traced from battery, winding of relay 21, conductor 27, conductor 430, wiper 428 of switch P3, conductor 427, wiper 426 of switch P1, conductor 425, contacts 424 of relay 310, contacts 423 of relay 313, conductor 422, contacts 100 of relay 99, conductor 765, contacts 35 764 of relay 754 to ground on contacts 760 of transfer relay 755 and through contacts 762 of relay 753 to the same ground. The circuit for operating magnet 570 may be traced from battery, winding of relay 570, contacts 569 of shift relay 40 521, conductor 766, contacts 763 of relay 754 to ground on contacts 760 of transfer relay 755; and the circuit for operating magnet 524 may be traced from battery, winding of magnet 524, contacts 568 of shift relay 521, conductor 765A, contacts 761 of 45 relay 753 to ground on contacts 760 of transfer relay 755. In the manner previously described, the operation of magnets 570 and 524 and the energization of operating magnet 27 cause the hundreds quantity indicator 540 to be positioned 50 so as to display the digit 9, designating 900 shares.
- During the third revolution of the distributor brush 800 the recording relay 733 in group N3 is operated and locked. When the transfer relay 771 is thereafter released, circuits are completed 55 for energizing the operating magnet 23 associated with the fractions indicator 530E on the last shelf of stock Q2, and for operating the magnet 515C associated with the code selector 514 mounted on the fractions shaft 507, which with 60 other code selectors controls the movement of the shaft. The circuits for operating these magnets have been previously traced. When these magnets operate, the fractions price indicator 530E on the last shelf of stock Q2 is thus positioned, in the manner previously described, to display the fraction $\frac{1}{2}$. As the hundreds price indicator 530, the tens price indicator 530B, and the units price indicator 530C are already set to display the digits 1, 2 and 3 respectively, the desired price quotation 123 $\frac{1}{2}$ is, therefore, posted.
- From the examples given above, it is apparent that any one of the groups of indicators for displaying quotations relating to stocks Q, Q1, Q2, Q3, etc., can be selected in response to impulses 75

transmitted from the master station, and that any of the indicators in the selected group can be predeterminately operated to display any desired price quotation, on any of the several shelves, and to display the quantity of shares sold.

The nominating operations, which have been described as taking place during any one or more of the first three revolutions of the receiving distributor, serve to permit the stock quotation signals to be transmitted in the order of their appearance on the ticker tape, as will be evident from an examination of the sequence in which the recording relay groups are associated with the receiving distributor. In addition, if certain elements of a new quotation are the same as the corresponding elements of the previous quotation, the nominating operations allow the transmission of only the changed elements in the new quotation, these latter elements being transmitted in their normal order without requiring the sending operator to send skipping or "fill-in" signals in the place of the deleted quotation elements.

25 Considering first the transmission of the quotation signals in their normal order, it is apparent from the description of operation given that, when the nominating operations have been effected, the stock selection signals, the shelf selection signals, the quantity and the price selection signals are transmitted in the order enumerated.

Considering next the transmission of only the changed elements of a quotation, if the new quotation is on the same stock as the previous quotation, and if no shelf and quantity selection is required, after the nominating operations the sending operator can send only the price signals corresponding to the changed price, and these signals, without any further action on the part of the sending operator, will be effected to set the proper price indicators of the selected indicating mechanism.

It is evident that the nominating operations 45 serve a useful function in facilitating the rapid transmission of the quotation signals by allowing the quotation elements to be sent in their natural order, even though some of the elements of a quotation appearing upon the ticker tape are 50 not transmitted.

As shown, the various groups of dials are mounted on drive shafts, schematically illustrated. The invention is not to be limited to this precise arrangement. In actual practice, 55 spiral gears may be employed for proper transmission and driving of the dial actuating shafts. The schematic illustrations are merely to facilitate a comprehensive understanding of the system disclosed. Hence, no unnecessary limitations should be understood and the appended 60 claims should be construed as broadly as the state of the art permits.

I claim:

1. In an automatic stock quotation board, a 65 distributor controlled by impulses transmitted over a single channel from a master station, a plurality of storage relay groups arranged in a predetermined order, means controlled by said distributor in accordance with received signals for 70 selecting predetermined storage relay groups in the opposite order, and means thereafter controlled by said distributor for causing impulses received thereby to be stored in the selected storage relay groups, said impulses being stored in 75 one of said groups at a time, and in an order

corresponding to the order in which said groups are arranged.

2. In an automatic stock quotation board, a plurality of indicator groups each group having a plurality of indicators adapted to display quotations on a particular stock, a distributor controlled by received impulses, a plurality of storage relay groups, means controlled by said distributor for predetermining in one order the storage relay groups to be associated with said distributor, other means likewise controlled by said distributor for associating the predetermined storage relay groups with said distributor in a different order and for causing impulses received by said distributor to be stored in each of the associated groups, and means for utilizing the stored impulses from the several storage relay groups in the order of their association with said distributor to select an indicator group corresponding to a particular stock and to position 20 predetermined indicators in said group.

3. In an automatic stock quotation board, a first and a second indicator group, each group having a plurality of indicating mechanisms each adapted to display quotations on a particular stock, each mechanism comprising a plurality of indicators, a distributor controlled by received impulses, a plurality of storage relay groups, at least one of said storage relay groups controlling the selection of said first indicator group and at 30 least another of said storage relay groups controlling the selection of said second indicator group, means controlled by said distributor for selecting in one order predetermined storage relay groups, including the group associated with the first indicator group, other means likewise controlled by said distributor for associating the selected storage relay groups with said distributor in an order differing from the order of their selection and for causing impulses received by 40 said distributor to be stored in each of the associated groups, and means for utilizing the impulses stored in the storage relay group associated with the first indicator group to select an indicating mechanism in said group and for utilizing the impulses stored in the remaining groups to position predetermined indicators in 45 said mechanism.

4. In an automatic stock quotation board, a first and a second indicating group, each group 50 having a plurality of indicating mechanism each adapted to display quotations on a particular stock, each mechanism comprising a plurality of indicators, a distributor controlled by received impulses, a plurality of storage relay groups, at 55 least one of said storage relay groups controlling the selection of the first indicator group and at least another of said storage relay groups controlling the selection of the second indicator group, means controlled by said distributor for 60 selecting in one order predetermined storage relay groups including the group associated with the second indicator group, other means likewise controlled by said distributor for associating the selected storage relay groups with said distributor in an order differing from the order of their selection and for causing impulses received by 65 said distributor to be stored in each of the associated groups, and means for utilizing the impulses stored in the storage relay group associated with the second indicator group to select one 70 of the indicating mechanisms in said group and for utilizing the impulses stored in the remaining storage relay groups to position predetermined indicators in said mechanism.

5. In an automatic stock quotation board, a first, second and third indicator group each group having a plurality of indicating mechanisms each adapted to display quotations on a particular stock, each mechanism comprising a plurality of indicators, a distributor controlled by received impulses, a plurality of storage relay groups, at least one of said storage relay groups controlling the selection of said first indicator group and at least another storage relay group controlling the selection of the second indicator group, means controlled by said distributor for selecting in one order predetermined storage relay groups, including the groups associated with the first and second indicator groups, other means likewise controlled by said distributor for associating the selected storage relay groups with said distributor in an order differing from the order of their selection and for causing impulses received by said distributor to be stored in each of the associated groups, and means for utilizing the impulses stored in the storage relay groups associated with the first and second indicator group to select an indicating mechanism in the third indicator group and to utilize the impulses stored in the remaining storage relay groups to position predetermined indicators in the selected mechanism. 5 10 15 20 25 30 35 40 45 50 55 60 65 70 75
6. In an automatic quotation board, a plurality of indicator groups each adapted to display quotations on a particular stock, each group comprising a plurality of price indicators divided into shelves, a distributor controlled by received impulses, a plurality of storage relay groups, at least two of said groups controlling the selection of any indicator group, at least another group controlling the shelf selection in the selected indicator group, and other storage relay groups controlling the positioning of predetermined indicators on the selected shelves, means controlled by said distributor for selecting in one order predetermined storage relay groups, including one or both indicator selection groups, said shelf selection group and certain of said indicator positioning groups, other means likewise controlled by said distributor for associating the selected storage relay groups with said distributor in an order differing from the order of their selection and for causing impulses received by said distributor to be stored in each of the associated groups, and means for utilizing the impulses stored in the selected storage relay groups to select a predetermined indicator group, to select predetermined shelves in said group, and to position predetermined indicators on the selected shelves. 30 35 40 45 50 55 60 65 70 75
7. In an automatic quotation board, a plurality of indicator groups each adapted to display quotations on a particular stock, each group comprising a plurality of price indicators divided into a "last" shelf and a plurality of other shelves, a distributor controlled by received impulses, a plurality of storage relay groups, at least two of said groups controlling the selection of any indicator group, at least another group controlling the selection of the shelves other than the "last" shelf in the selected indicator group, and other storage relay groups each controlling the positioning of a predetermined indicator on the "last" shelf and a corresponding indicator on each of the selected shelves in the selected indicator group, means controlled by said distributor for selecting in one order predetermined storage relay groups, including one or both indicator selection groups, said shelf selection groups, and certain of said other groups, other means likewise controlled by said distributor for associating the selected storage relay groups with said distributor in an order differing from the order of their selection and for causing impulses received by said distributor to be stored in each of said associated groups, and means for utilizing the impulses stored in the selected storage relay groups to select a predetermineded indicator group, to select predetermined shelves, except the "last" in said group, and to position predetermined indicators on the "last" shelf and corresponding indicators on the selected shelves. 5 10 15 20 25 30 35 40 45 50 55 60 65 70 75
8. In a stock quotation system, a stock quotation board having a plurality of stock display units, each unit having a plurality of shelves, invariably selectable price display means on one of said shelves, and selectable price display means on the remainder of said shelves each of said price display means having a plurality of indicators, an operating relay individual to each of the indicators on said invariably selectable shelf, an operating relay common to the indicators on the other price shelves, a shaft common to corresponding indicators on each of said price shelves, a plurality of selective circuits for controlling said operating relays, stock selecting means for extending said selective circuits to a predetermined unit, shelf selecting means for completing a circuit for energizing the operating relays on said invariably selectable shelf, price selective means for completing selective circuits for energizing the operating relays on said selectable shelves, code selector devices for variably positioning said shafts, said devices being, in turn, positioned by said price selecting means, means for positioning any of said price indicators by the movement of its associated shaft and the energization of its operating relay, and a distributor for selectively operating said price selecting means. 15 20 25 30 35 40 45 50 55 60 65 70 75
9. In a stock quotation system, a stock quotation board having a plurality of stock display units, each of said units having a plurality of shelves, quantity display means on one of said shelves, invariably selectable price display means on another, and selectable price display means on the remainder of said shelves, a plurality of selective circuits for operating any of said display means, stock selecting means for extending said selective circuits to a predetermined display unit, shelf selecting means for selecting one of said selectable price display means of said unit, quantity selecting means for operating the quantity display means of said unit, price selective means for operating the invariably selectable and the selectable price display means of said units, and a distributor for selectively operating the enumerated selector means. 45 50 55 60 65 70 75
10. In a stock quotation system, a stock quotation board having a plurality of stock display units, a plurality of groups of indicators for each unit, a drive shaft mechanism and selective circuits for positioning said indicators, means for operating said drive shaft mechanism and completing said selective circuits to effect display of a quotation of a predetermined stock by said indicators, means effective after the positioning of said indicators for restoring said drive shaft mechanism to normal, for dis-establishing said selective circuits and for retaining said circuits in association with the selected stock display unit, and means for predetermined upon reception of the next quotation whether said selective circuits are to be extended to a different display unit and 70 75

whether said indicators are to be moved to a new position.

11. In a stock quotation system, a stock quotation board having a plurality of stock display units, a plurality of groups of indicators for each unit, a drive shaft mechanism and selective circuits for positioning said indicators, means for operating said drive shaft mechanism and for completing said selective circuits to position said indicators to display a quotation of a predetermined stock, means effective upon the positioning of said indicators for restoring said drive shaft mechanism, for dis-establishing said selective circuits and for retaining said circuits in association with the selected stock display units, and means for displaying the next received quotation by setting only the indicators in respect to which the new quotation differs.

12. In an automatic stock quotation board, in combination, a plurality of groups of stocks having either a single letter odd, a single letter even or a double letter designation, means for selecting a stock having one of said designations, code selector devices for operating said last-mentioned means, a plurality of storage relays for selectively operating said code selector devices, a distributor for operating said storage relays, translation control relays for predetermining which of said storage relays are to be connected to said distributor, and switching means for selectively operating said translation control relays.

13. In an automatic stock quotation board, a plurality of indicator groups, each group having a plurality of indicators for displaying quotations on a particular stock, each stock being selectively represented by impulses of a single designation in one of two arrangements or a combination of said single designations, a distributor controlled by impulses transmitted over a single channel from a master station, a plurality of storage relay groups arranged in a predetermined order, means controlled by said distributor for causing stock representing impulses and other impulses received by said distributor to be selectively stored in said storage relay groups, and means for utilizing impulses stored in any particular relay group before received impulses are stored in a succeeding group, said means for utilizing the impulses stored in said groups comprising means operated by stored impulses representing the particular stock, for selecting the indicator group corresponding thereto, and means operated by the remaining stored impulses to position predetermined indicators in said selected group.

14. In an automatic stock quotation board, a plurality of indicator groups, each group having a plurality of indicators for displaying price quotations on a particular stock, the price indicators of each group being divided into shelves and having a plurality of digit display units on each shelf, a distributor controlled by impulses transmitted over a single channel from a master station, a plurality of storage relay groups arranged in predetermined order, means controlled by said distributor for selecting predetermined ones of said storage relay groups, other means likewise controlled by said distributor for causing impulses received by said distributor to be stored successively in the selected relay groups, means for utilizing the impulses stored in certain of said relay storage groups to select an indicator group and shelf corresponding to a particular stock, and means for utilizing the impulses stored in certain of the remaining of said selected impulse

storage groups to position selected predetermined ones of said price digit display units.

15. In an automatic stock quotation board, a plurality of indicator groups, each group being adapted to display quotations on a particular stock, each stock being selectively represented by impulses of a single designation in one of two arrangements or a combination of said single designations, a distributor controlled by impulses transmitted over a single channel from a master station, a plurality of storage relay groups arranged in predetermined order, means controlled by said distributor for selectively conditioning the first two of said storage relay groups either singly in proper order or in combination dependent upon the nature of the stock representing signal, other means controlled by said distributor for selecting other relay storage groups, means likewise controlled by said distributor for causing impulses received by said distributor to be stored in the selected relay groups, a switch for selecting from said indicator groups any indicator group to display quotations on a selected stock, a code selector means controlled by impulses stored in said first and second impulse storage means for causing said switch to select a predetermined one of said indicator groups, and means operative in response to impulses stored in the other of said signal storage relay groups for positioning the indicators in said selected indicator group.

16. In an automatic stock quotation board, a plurality of indicator groups each adapted to display quotations on a particular stock, each group including a plurality of quantity digit indicators, a plurality of quantity digit shafts common to the quantity digit indicators of the indicator groups, a distributor controlled by impulses transmitted over a single channel from a master station, a plurality of storage relay groups arranged in a predetermined order, the first two of said storage groups serving to store stock representative signals, and others of said signal storage groups serving to store quantity digit indicating signals, means controlled by said distributor for selecting the particular relay storage groups indicating a stock and for selecting particular ones of said quantity digit storage relay groups, means controlled by said distributor for selecting certain of said stock representing and quantity digit indicating storage relay groups, other means likewise controlled by said distributor for causing stock representing and quantity digit indicating impulses received thereby to be stored successively in the selected storage relay groups, means for utilizing the impulses stored in said first two storage relay groups to select an indicator group adapted to display quotations on a predetermined stock, and means for utilizing the selected ones of said digit storage relay group to set the selected ones of said quantity shafts to a predetermined position and to cause the selected quantity digit indicators in the selected indicator group to rotate to a position corresponding to the set position of said selected shafts.

17. In an automatic stock quotation board, a plurality of indicator groups each adapted to display quotations on a particular stock, each group having previous close, open, high, low and last price shelves, each shelf comprising hundreds, tens, units and fractions indicators, an operating magnet common to the indicators on each price shelf except the last, an operating magnet individual to each of the indicators on the last shelf, hundreds, tens, units and fractions price shafts common to the hundreds, tens, units and frac-

tions price indicators on the board, a distributor controlled by impulses transmitted over a single channel from a master station, a plurality of storage relay groups arranged in a predetermined order, means controlled by said distributor for selecting the first, second and third of said storage relay groups and for selecting others of said storage relay group corresponding to the integers and fraction of a quoted price dependent upon the received signals, other means likewise controlled by said distributor for causing impulses received thereby to be stored successively in the selected storage relay groups, means for utilizing the impulses stored in the first and second of said groups to select an indicator group adapted to display quotations on a predetermined stock,

means for utilizing the impulses stored in the third group to actuate the common operating magnet associated with predetermined shelves in the selected indicator group, and means for utilizing the impulses stored in the other groups for setting selected price digit shafts to a predetermined position and to actuate the operating magnet individual to the selected price digit indicators on the "last" shelf, the actuation of said operating magnets causing the selected price digit indicators on the selected shelves and on the "last" shelf of the selected indicator group to be set to the position of the selected price digit shaft. 5 10

CLYDE SMITH. 15
